UNITED STATES PATENT OFFICE.

HUBERT S. TURNER, OF SAN DIEGO, CALIFORNIA.

TELEPHONY.

Application filed February 27, 1915. Serial No. 11,046.

To all whom it may concern:

Be it known that I, HUBERT S. TURNER, a citizen of the United States, residing at San Diego, in the county of San Diego and 5 State of California, have invented certain new and useful Improvements in Telephony, of which the following is a specification.

This invention relates to telephone exchange systems, some features thereof being 10 of particular service in connection with switchboard systems of the central energy multiple type, to which, however, the invention is not to be restricted, and in some of its aspects constitutes improvements on features of a telephone system disclosed in my U. S. Patent No. 1,128,262, granted February 9, 1915.

The present invention has for its broad objects the provision of means whereby the 20 necessity for the finger contact device and special calling plug contact disclosed in the aforementioned application, is done away with; adaption of the automatic ringing system disclosed in said application to party 25 line ringing; the provision of improved means of selectively ringing call bells on party lines; the provision of improved means of operating supervisory signals, whereby a plurality of signals are produced 30 by a lesser number of lamps; the provision of improved means of obtaining a "waiting" connection with a busy line; the provision of improved means for preventing a telephonic connection to a busy line; the provision 35 of automatic supervision, whereby such supervision is performed by a special supervisory operator. Other objects will be apparent from the specification.

In order to more fully describe my invention, reference will be had to the accompanying drawings forming a part of this specification and wherein,

Figure 1 is a diagram illustrating in one form the various features of my invention above mentioned;

Figure 2 a modification of the calling link connector shown in Figure 1;

Figure 3 a modification of the party line ringing interrupters shown in Figure 1;

Figure 4 a diagram illustrating principally a modification in which the functions of the operator's relay and the controlling relay illustrated in Figure 1, are combined in one relay;

Figure 5 a diagram showing in modified form certain features of my invention, illus-

trated in Figure 1, and in addition thereto means for effecting a delayed release of the operator's relay;

Figure 6 a diagram showing a modified way of obtaining the delayed release of the operator's relay, substituting a plug seat switch for the controlling relay shown in Figure 5;

Figure 7 a diagram illustrating a form 65 of my invention wherein means are provided whereby a special operator attends to the supervision of the telephonic connections established by the link connectors;

Figure 8 a diagram illustrating a special 70 cord circuit to be used by the special operator mentioned in connection with Figure 7;

Figure 9 a diagram illustrating a modification of my invention wherein the supervisory 75 lamps are operated in a different way to those shown in the preceding figures;

Figure 10 a diagram illustrating a modification of my invention wherein but one supervisory lamp or signal is used which is 80 displayed when the established connection is to be taken down;

Figure 11 a diagram illustrating a manually operated means for energizing the 85 operator's relay illustrated in the preceding figures and an elapsed time mechanism for de-energizing the same.

Figure 12 a diagram illustrating an apparatus for obtaining the disconnection of the operator's telephone set from a calling 90 line previous to the connection being completed through to the called line.

Figure 13 a diagram illustrating an arrangement of circuits and apparatus whereby the described system is adapted to trunk 95 line operation;

Figure 14 a diagram illustrating a form 100 of busy test apparatus used with the circuits shown in Figures 13 and 15;

Figures 15, 16 and 17 diagrams illustrating 105 various embodiments of my invention adapted to a trunking system;

Figure 18 a diagram illustrating a modification of my invention wherein the link connector shown is used for connecting a 110 calling party to a trunk line only;

Figure 19 a diagram illustrating a modification of the trunking adaptation specially adapted to be used with the link connector shown in Figure 18, but which may be used 115 with the other link connectors illustrated in the preceding figures.

Referring first to Figure 1, 1 represents a telephone sub-station which includes a telephone receiver 2, a transmitter 3, a switch-hook 4, a call bell 5, a condenser 6, 5 and primary 7 and secondary 8 of an induction coil. The elements 3 and 7 are included in a bridge of the telephone line, which bridge is open when the telephone receiver is upon the switch-hook 4 and which 10 bridge is closed by the switch-hook 4, when relieved of the weight of the telephone receiver. The elements 5 and 6 are included in another bridge permanently continuous with respect to alternating current, but 15 non-continuous with respect to direct currents. The type of sub-station outfit shown is one that I have selected for the purpose of illustrating the invention, but it is to be understood that I do not limit myself to 20 the form of sub-stations apparatus shown, for it will be seen as the description of the invention is proceeded with, that the operation of the system does not depend upon the peculiar sub-station outfit shown. Sub-sta- 25 tion 1 is connected to the exchange in the form of the invention shown by means of metallic circuits, whose limbs 9 and 10 are connected with the line springs or talking contacts of spring jacks 11 and 12. A plu- 30 rality of spring jacks is shown in multiple relation with each line, the lowermost spring jack 12 constituting the answering jack, while the remaining jacks 11 constitute multiple jacks. The limbs 9 and 10 also termi- 35 nate in contacts on the right and left armature switches of cut-off relay 13, the limbs of each telephone line being normally connected by means of said armature switches and the contacts normally engaged thereby 40 with a line relay 14, the limb 9 being connected with the left hand winding and the limb 10 being connected with the right hand winding of said relay, the other terminals of the windings of said relay being connected 45 through grounded battery 15. Line relay 14 is actuated by the removal of the telephone receiver at sub-station 1 from its supporting switch-hook by means of a circuit which may be traced as follows: from transmitter 50 3, through line 9, left hand armature switch and normal contact of cut-off relay 13, left hand winding of line relay 14 to the live pole of grounded battery 15, through said battery to ground, through resistance 16, the 55 right hand winding of line relay 14, right hand normal contact and armature switch of cut-off relay 13, line 10, primary 7, switch-hook 4, completing the circuit through transmitter 3. This actuation of line relay 60 14 causes its armature switch to close a circuit through line lamp or signal 17 which may be traced from ground through said resistance 16, said armature switch and engaged contact of line relay 14, said line lamp or signal, interrupter 18 and its brush and 65

grounded battery 15 to ground, thus completing the circuit.

Interrupter 18 consists of a rotating metallic member with one or more insulating segments, there being a shunt circuit around 70 said interrupter through resistance 19. Hence the current passing through re- sistance 16 from line lamp or signal 17 is a variable one though not intermittent and the current from grounded battery 15 passing 75 through the same resistance to the described line circuit including primary 7 is also made variable thereby. This variable current sets up an alternating current in sec- 80 ondary 8 which is heard as an audible signal in telephone receiver 2 which is in circuit with said secondary. It will be seen that if the circuit was open through limbs 9 and 10 there would be no path for the described 85 variable current and hence no audible sig- 90нал would be produced; and if the circuit was open through line lamp or signal 17 the current passing through resistance 16 would not be a variable one and again no audible signal would be produced. Therefore, the 95 production of said audible signal in said receiver 2 is an assurance to the party at sub- station 1 that the line wires are in working condition and that the line lamp or signal at the central exchange has been displayed. 95

Having observed the displayed line signal of the calling sub-station the operator inserts answering plug 20 into answering jack 12 corresponding to the calling sub-sta- 100 tion. This action closes a circuit which may be traced as follows: from the grounded terminal of cut-off relay 13, through the winding of said relay, sleeve of answering jack 12, sleeve contact of answering plug 20, left hand winding of answering super- 105 visory relay 21, winding of operator's relay 22, contact and armature switch of controlling relay 23 to the live pole of ground- 110 ed battery 15, completing the circuit through the same. The actuation of cut-off relay 13, due to the current flowing through this traced circuit breaks the circuit from sub- 115 station 1 through line relay 14 and line lamp or signal 17 therefore resumes its nor- 120 mal condition due to the consequent dis- engagement of the armature switch of line relay 14 from its contact. 115

The actuation of operator's relay 22, due to the current flowing through the same traced circuit, causes its various armature 120 switches to be attracted.

The actuation of answering supervisory relay 21, due to the current flowing through the same traced circuit, closes another circuit which may be traced as follows: from ground through battery 15, "talking" in- 125 terrupter 24, alternate contact and armature switch of actuated answering supervisory relay 21, winding of answering relay 25, sleeve contact of answering plug 20, sleeve of 130

answering jack 12, and winding of cut-off relay 13, completing the circuit to ground. The actuation of answering relay 25, due to the current flowing through the circuit just 5 traced causes its various armature switches to be attracted.

A circuit therefore may be traced as follows: from ground through repeating coil winding 26, uppermost armature switch and 10 engaged contact of the two top ones of answering relay 25, ring contact of answering plug 20, ring contact spring of answering jack 12, limb 9, transmitter 3, switch-hook 4, primary 7, limb 10, tip spring of answering jack 12, tip contact of answering plug 20, right hand winding of answering supervisory relay 21 and the non-inductive resistance in multiple relation thereto, lowermost engaged contact and armature switch 20 of the three bottom ones of answering relay 25, repeating coil winding 27 and grounded battery 15, completing the circuit to ground. The current thus allowed to flow through 25 the right hand winding of answering supervisory relay 21 is sufficient to maintain its armature switch disengaged from its normal contact when current ceases to flow through the left hand winding.

At the same time primary 7 at sub-station 30 1 receives operating current from grounded battery 15 and receiver 2 is placed in inductive relation with windings 26 and 27 of the repeating coil. Therefore, the party at sub-station 1 is telephonically connected with 35 the operator who has responded to the line signal, as the actuation of operator's relay 22 connected operator's telephone receiver 28 to the line of the calling sub-station. A circuit for this connection may be traced as 40 follows: from repeating coil winding 26 through the contact and engaged uppermost armature switch of the two top ones of operator's relay 22, secondary of operator's induction coil 31, receiver 28, condenser 32, 45 bottom armature switch and engaged left hand contact of operators relay 22 and repeating coil winding 27.

When cut-off relay 13 is actuated, simultaneously with the actuation of answering supervisory relay 21 and operator's relay 22, the audible signal in receiver 2 at sub-station 1 ceased, as limbs 9 and 10 were disconnected from the variable current flowing through resistance 16. The cessation of 50 this audible signal may be used as a notification to the party at sub-station 1 that an exchange operator is connected to his line and is ready to receive the number he wishes to be connected to, as answering relay 55 25 is actuated as soon as answering supervisory relay 21 is actuated, thereby completing the telephonic connection between the calling party and the answering operator. Therefore, the usual verbal inquiry of the 60 operator may be dispensed with. How-

ever, the operator may converse with the calling party, if desired or if necessary, by means of operator's transmitter 33 and primary 34 of the operator's induction coil.

Having been told the number the calling 70 party desires to be connected with, the operator tests the called for line by touching the sleeve of one of the multiple jacks 36, associated with said line, with the tip contact of calling plug 35 in a manner well 75 known in the art.

(The busy tests will be described herein-after.)

If the line tests "not busy," calling plug 80 35 is inserted in multiple jack 36, establishing a circuit which may be traced as follows: from the grounded terminal of cut-off relay 37, through the winding of the same, sleeve of multiple jack 36, sleeve contact of calling plug 35, spring switch 38 and engaged contact of calling relay 39, winding of ringing relay 40, right and left hand contacts connected by the bottom armature switch of actuated operator's relay 22 and winding 27 of the repeating coil, completing 85 the circuit through grounded battery 15. The current flowing through this circuit causes cut-off relay 37 to actuate removing line relay 41 from the control of the sub-stations connected therewith. Ringing relay 40 is also energized by said current and its various armature switches are attracted. The engagement of the top armature switch of said relay with its two contacts closes two 90 circuits first and then operates spring switches 42, 43 and 44 afterwards. The two bottom armature switches of said relay are not attracted until after said engagement of the top armature switch has taken place.

Said circuits may be traced as follows: 100 first, from the upper terminal of the winding of said relay through said armature switch and the left hand engaged contact, upper winding of controlling relay 23, spring switch 42, (which is disengaged from its normal contact) spring switch 43, (which in turn is disengaged from its normal contact) middle one of the three bottom armature switches and engaged contact of 105 answering relay 25, "ringing" interrupter 45, and grounded battery 15 completing the circuit through the circuit already traced through the winding of cut-off relay 37.

The second circuit may be traced from the grounded terminal of magnetic clutch 46 of 110 party line ringing key 47, release key 48, the winding of said clutch, supervisory lamp 49, right hand contact and engaged top armature switch of ringing relay 40, and the left hand engaged contact of the same, completing the circuit to ground through the circuit already traced through the upper winding of controlling relay 23 and "ringing" interrupter 45. The current thus allowed to flow through said winding energ- 115 120 125 130

4

gizes relay 23 and its armature switch disengages its contact, opening the circuit through the winding of operator's relay 22 and left hand winding of answering supervisory relay 21. The consequent de-energization of operator's relay 22, releases its various armature switches, removing the operator's telephone set from telephonic connection with the calling sub-station and 10 opening the energizing circuit of ringing relay 40, which has been traced from the upper terminal of the winding of said relay through the two contacts of the bottom armature switch of operator's relay 22. However, current still flows through the winding of ringing relay 40, to maintain the same actuated, by way of the circuit traced 15 through the upper winding of controlling relay 23.

20 Answering supervisory relay 21 remains actuated, due to the described circuit through its right hand winding. Cut-off relay 13, also remains actuated, due to the also described circuit through the winding of 25 answering relay 25.

The insertion of calling plug 35 into multiple jack 36, also closed another circuit which may be traced as follows: through the described circuit from the grounded 30 terminal of cut-off relay 37 to the lower winding of controlling relay 23, completing the circuit through grounded battery 15. This lower winding constitutes a locking winding and is of a preferably extremely high 35 resistance and is such that the current passing through the same, while not sufficient to cause the disengagement of the armature switch of said relay from its contact, is sufficient to maintain the same disengaged 40 after said disengagement has been accomplished by the current flowing through the upper winding of said relay.

The operation of the two bottom armature 45 switches of ringing relay 40, impresses ringing current on the line of the called for sub-station in the manner fully described in my aforesaid patent, wherein is also described the means whereby calling supervisory relay 50 and calling relay 39 are actuated 50 when the called for sub-station responds to its calling signal.

The application of the aforesaid ringing system to party line ringing will now be described.

55 The aforesaid connection with multiple jack 36, as described, related to a line with a single sub-station associated therewith. If the calling party had called for a sub-station on a party line; previous to inserting calling plug 35 in multiple jack 36, the operator would have depressed the corresponding party line key. In the party line ringing system illustrated in Figure 1, six ringing keys are illustrated diagrammatically, numbered respectively from 51 to 56; both in-

clusive. Numbers 51, 52, 55 and 56 being single "break" and "make" keys and numbers 53 and 54 being double "break" and "make" keys, so arranged that their actuation also operates either key number 51 or 70 52, as the case may be.

The hereinbefore described actuation of answering relay 25, (previous to the actuation of ringing relay 40) closed a circuit which may be traced as follows: from the live pole of grounded battery 15, through "ringing" interrupter 45, contact and engaged middle armature switch of the three bottom ones of answering relay 25, spring switch 43 and normal contact of ringing relay 40, supervisory lamp 57, winding of magnetic clutch 46, release key 48 completing the circuit to ground. Such magnetic clutches are well known in this art and need not be herein described in detail. The current flowing through the winding of said clutch is sufficient to maintain the switch springs of the party line ringing keys engaged with their alternate contacts, after the same have been so engaged manually. If the party called for is represented by one ring of positive pulsating current on the limb of the line connected to the tip spring of multiple jack 36, then the operator would depress key 51 before inserting calling plug 35 into multiple jack 36. The current flowing through the winding of magnetic clutch 46, is not interrupted by the described actuation of ringing relay 40, though after said actuation the operating current for the magnetic clutch flows through supervisory lamp 49 instead of supervisory lamp 57. This result is obtained by means of a circuit which may be traced as follows: from the live pole of grounded battery 15, through waiting interrupter 58, contact and engaged lowermost armature switch of the two top ones of answering relay 25, normal contact and spring switch 42 of ringing relay 40, upper winding of controlling relay 23, the two contacts of the top armature switch of ringing relay 40, which are connected together by the operation of said armature switch, supervisory lamp 49 and winding of magnetic clutch 46, completing the circuit to ground through release key 48. As hereinbefore described, the top armature switch of ringing relay 40, engages its two contacts before the operation of spring switches 42, and 43, therefore the last described circuit through supervisory lamp 49 is made previous to the opening of the circuit through supervisory lamp 57. As spring switch 43 engages spring switch 42 before the latter becomes disengaged from its normal contact, connecting said spring switch to "waiting" interrupter 58, the current flowing through supervisory lamp 49 also is not interrupted, notwithstanding the completed actuation of ringing relay 40 substitutes current from "ringing" 130

interrupter 45 for current from "waiting" interrupter 58.

Having depressed party line ringing key 51 and inserted calling plug 35 into multiple 5 jack 36 a circuit for the proper ringing current may be traced as follows: from the grounded brush of alternating current ringing generator 59, through the latter, interrupter 60, brush 61, interrupter 62 and 10 its brush, alternate contact and engaged spring switch of key 51, alternate contact and engaged uppermost armature switch of the two bottom ones of ringing relay 40, non-inductive resistance 63, normal 15 contact and left spring switch of key 54, normal contact and right spring switch of key 53, tip contact of calling plug 35, tip spring of multiple jack 36, limb 64 of the called sub-station line, condensers and biased 20 bells at the sub-stations associated with said limb, limb 65, ring spring of multiple jack 36, ring contact of calling plug 35, left spring switch and engaged normal contact of key 53, right spring switch and engaged 25 normal contact of key 54, winding 29 of the repeating coil, spring switch 44 and engaged contact of ringing relay 40, spring switch and normal contact of key 55 and spring switch and normal contact of key 56, completing 30 the circuit to ground. Due to the ringing current so impressed upon the line, call bells or annunciators 66, 67 and 68 (which are so biased that they respond only to positive current of high voltage impressed 35 upon limb 64) are operated.

The metallic portion of interrupter 60 is only in contact with brush 61 during a period which represents a trifle less than one-quarter of the revolution of said interrupter. 40 When the center of the exposed metallic portion of said interrupter is engaged with brush 61, the voltage of the positive current produced by alternating current generator 59 and delivered to said interrupter is at its maximum, the insulated portion of said interrupter being engaged with said brush during the period when the voltage of the positive current delivered to said interrupter is increasing or decreasing and the current 45 changing from positive to negative. Another circuit may be traced through alternating current generator 59, as follows: from the grounded brush of said generator, through the latter and primary of transformer 69 completing the circuit to ground. Said transformer is of the set-down type, so that the voltage produced in the secondary thereof is so low that the current flowing through said secondary will not operate the 50 call bells or annunciators of the lines which may be connected to said secondary, even though said bells may be biased to the polarity taken off from said secondary. A circuit may be traced from ground, through said

secondary, interrupter 70, brush 71, and 65 thence over the same route followed by the current delivered by interrupter 60. Interrupter 70 is a counterpart of interrupter 60, only the center of its exposed metallic portion engages brush 71 when the voltage of 70 the negative current produced in the secondary of transformer 69 and delivered to said interrupter is at its maximum. Both interrupters 60 and 70 are so mounted that they 75 revolve in synchronism with the armature of ringing generator 59, being preferably mounted on the same shaft. Therefore the current delivered to interrupter 62 is an alternating one, though the voltage of the positive alternation is that of generator 80 59 while the voltage of the negative alternation is that of the secondary of step down transformer 69. Instead of transformer 69 it will be seen that another generator producing a voltage lower than that of generator 85 59 might be used, the connection to interrupter 70 being the same as that from generator 59 to interrupter 60. As the use of the transformer entails the use of but one generator, I have so illustrated the system 90 in the drawing.

A circuit has been traced from interrupter 62 through limb 64 and the biased call bells or annunciators associated with said limb, and it has been mentioned that call bells or 95 annunciators 66, 67, and 68 alone are operated. This action is due to the fact that while negative current is delivered to limb 64 from transformer 69 through interrupter 62, its voltage is so low that biased bells 72, 100 73 and 74 (which are adjusted to be operated only by the delivery of negative current to said limb 64 of the voltage of alternating current ringing generator 59) are not operated thereby. However, the voltage of said 105 negative current is sufficient to cause the condensers in series with call bells or annunciators 66, 67 and 68 to allow the passage of the high voltage positive current, thereby causing the operation of said bells 110 or annunciators. This I claim is a novel means of operating biased bells or annunciators or of selectively ringing a plurality of call bells or annunciators when bridged in series with condensers across a party telephone line, for while the ringing current used is an alternating one in fact, in operation it is virtually a pulsating current.

Interrupter 62 revolves slowly so that the signals produced at the respective sub-stations 120 are intermittent ones, the length of the ringing and silent intervals being purely arbitrary and can be adjusted according to the respective size of the metallic and insulating segments of interrupter 62 and the speed of rotation of the latter. The ringing circuit as described produces "one ring" signals at 125 the sub-stations 66, 67 and 68, thereby indi-

cating which one of the three sub-stations was desired. If the calling party desired the sub-station responding to "two rings" the operator would have depressed key 56, as well as key 51. In which event the circuit for the ringing current which was traced to ground through keys 55 and 56 and their normal contacts, would have been traced through the spring switch of key 55 and its alternate contact and interrupter 75 to ground. Interrupters 62, 75, 76, 77 and 78 are preferably of the same size and so mounted that they all revolve at the same speed, and the insulating segments of interrupter 75 engage its brush when the respective brushes of interrupters 62, 77 and 78 are in engagement with the center of their respective metallic segments. In this way the ringing period is broken up into two periods by means of the insulating segments of interrupter 75. If "three rings" had been called for, then key 55 would have been depressed, instead of key 56 and the ringing period would have been broken up into three periods. It will be seen that "four rings" or any other desired number could be obtained in the same manner, also that the ringing signals produced by interrupters 75 and 76 could be made to consist of short and long rings by merely arranging the insulating segments of said interrupters accordingly.

Had the call been for either sub-station 72, 73 or 74, which require high voltage negative current connected to limb 64, then the operator would have depressed key 52 instead of key 51, at the same time depressing key 55 or 56 if the call was for two or three rings. The current delivered to limb 64, in that event, would have been that from interrupter 77, which is connected to brushes 79 and 80 of interrupters 60 and 70. As said interrupters are arranged to revolve at the same speed as the armature of alternating current ringing generator 59, brush 79 engaging the center of the metallic portion of interrupter 60, when the negative current delivered to said interrupter is at its maximum and brush 80 engaging the center of the metallic portion of interrupter 70 when the positive current delivered to said interrupter by the secondary of step down transformer 69 is at its maximum, the ringing current impressed on limb 64 by the depression of key 52, is the reverse of that impressed thereon by the depression of key 51, and therefore call bells or annunciations 72, 73 and 74 will be operated. Call bells or annunciations 66, 67 and 68 are not operated by the low voltage positive current so impressed upon said limb, as they are so adjusted as to require for their operation positive current of the potential of ringing generator 59.

Had the call been for either sub-station 81, 82 or 83, which require high voltage positive current to be delivered to limb 65, then the operator would have depressed key 53, instead of either key 51 or 52; at the same time depressing key 55 or 56 if the call was for two or three rings. By depressing key 53, the connections to the tip and ring contacts of calling plug 35 are reversed and at the same time actuating member 84, insulated from the springs, depresses key 51. By this means the ringing circuit traced through interrupter 62 is reversed and the current from said interrupter is impressed on limb 65 instead of limb 64.

Had the call been for either sub-station 85, 86 or 87, which require high voltage negative current to be delivered to limb 65, then the operator would have depressed key 54, instead of either key 51, 52 or 53; at the same time depressing key 55 or 56 if the call was for two or three rings. By depressing key 54, the connections to the tip and ring contacts of calling plug 35 are also reversed, and at the same time actuating member 88, insulated from the springs, depresses key 52. By this means the ringing circuit traced through interrupter 77 is reversed and the current from said interrupter is impressed on limb 65.

It will be noted that the code ringing is produced by keys which are not individual to each type of ringing current used, but instead are common to both types, regardless of the limb of the telephone line they may be connected to. I claim this as a distinct advantage over the usual type of automatic code ringing which requires code keys individual to the type of current used, as less keys are needed resulting in less expense, maintenance and occupied space on the key shelf of the switchboard. Also keys 55 and 56 can be used to furnish code ringing for lines requiring the regular alternating ringing current.

It should be understood that the described means whereby an alternating current is produced having a high potential alternation of one polarity and a low potential alternation of another polarity could be used without the association with battery interrupter 91 in which event the exposed metallic portions of interrupters 61 and 71 might be enlarged and the current taken off from the same during a complete alternation instead of about one half an alternation as hereinbefore described.

Had the call been for a one party line, then the operator would have inserted calling plug 35 into multiple jack 36, without depressing any ringing key. I claim this is a distinct advantage over those ringing systems which require a key to be depressed or manipulated for every connection made to a

called for line, as the operator's time is saved thereby, the majority of connections made through a switchboard being usually to non-party lines.

- 5 When such a connection is made, the ringing circuit may be traced from ground through ringing generator 59, interrupters 89 and 78, normal contact and spring switch of key 52, normal contact and spring switch 10 of key 51, whence the circuit proceeds over the course already traced. Interrupter 89 is different from interrupters 60 and 70, though it revolves at the same speed as they do, inasmuch as the exposed metallic portion 15 is adapted to engage its brush when both the positive and negative current delivered to said interrupter from ringing generator 59 is at its maximum. Therefore both the positive and negative current impressed upon 20 the called for line is of the potential of ringing generator 59, and the call bell or annunciator 5 in series with condenser 6 of a non-party line (as shown at sub-station 1) is operated thereby.
- 25 The return of the ringing current to ground, whichever ringing key or keys are depressed or manipulated, is always through winding 29 of the repeating coil and as telephone receiver 2, at sub-station 1, is in 30 inductive relation to windings 26 and 27 of said repeating coil the ringing signals are heard in said receiver by the party at said sub-station, thereby assuring him that the called for sub-station is being rung.
- 35 If code ringing is used the depression of the wrong code key would therefore be indicated to the calling party who would thereupon rectify the error.
- 40 The energization of controlling relay 23 and the consequent disengagement of its armature switch with its contact has been shown to take place when ringing relay 40 is actuated, due to the insertion of calling plug 35 into multiple jack 36. By making this 45 relay of a slow-acting type, by any of the mechanical, electrical or magnetic means well known in the art, operator's receiver 28 would remain bridged across repeating coil windings 26 and 27 until after the first ringing signal had been given. By this means the 50 operator would hear said ringing signal in the same way as the party at sub-station 1, the absence of said signal being an indication of an open line or faulty connection in the ringing circuit, and if code ringing is used would serve as a check on the correct key having been depressed or manipulated.
- 55 When the party at a called sub-station 60 responds to the calling signal (regardless of whether it is a party line or not) limbs 64 and 65 are connected together through the sub-station telephone apparatus, as described in relation to sub-station 1. (Said apparatus is not shown in association with the sub-station call bells for sake of clearness.) The
- call bell or annunciator 5 and condenser 6 up to this point allowed the passage of alternating current only through limbs 64 and 65, but now the passage of direct current is allowed as well and a new circuit is closed 70 which may be traced as follows: from ground at key 56 or interrupter 75 or 76, as the case may be, according to whether the ring has been a code or not, through said key or interrupter, engaged contact and 75 spring switch 44 of ringing relay 40, winding 29 of the repeating coil, keys 54 and 53 to either the tip or ring contact of calling plug 35, as the case may be, according to whether party line ringing keys 53 or 54 have 80 been depressed or not, one of the springs of multiple jack 36, one of the limbs of the line called for, primary 7, switch-hook 4, transmitter 3 (as shown at sub-station 1), the other limb of the line, other spring of multiple jack 36, either tip or ring contact of calling plug 35, keys 53 and 54, winding of calling supervisory relay 50, spring switch 90 and engaged armature switch of ringing 85 relay 40 and interrupter 91, completing the 90 circuit through grounded battery 15.
- 95 Interrupter 91 is a counterpart of interrupter 89 and revolves at the same speed, which is that of the armature of ringing generator 59, but is so mounted that its brush engages its exposed metallic portion only when the brushes of interrupters 60, 70 and 89 are in engagement with their insulating portions. It will therefore be seen that ringing current from interrupters 60, 70 and 89 can never pass through non-inductive resistance 63, winding of calling supervisory relay 50, spring switch 90 and engaged armature switch of ringing relay 40 and interrupter 91 to ground through 100 grounded battery 15, nor can direct current from said interrupter 91 ever pass through said interrupters 60, 70 and 89, but that alternating with each alternation of the 105 ringing current from ringing generator 59, direct current will be sent through said winding of calling supervisory relay 50 and alternating current through said non-inductive resistance 63, the circuits in both cases 110 being completed through the limbs of the called for line only.
- 115 The rapid intermittent direct current sent through the winding of calling supervisory relay 50, by way of interrupter 91, when the described circuit for direct current is closed at the called for sub-station, is sufficient to cause the energization of said relay and the consequent engagement of its armature switch with its alternate contact, which 120 closes a circuit which may be traced as follows: from the grounded terminal of cut-off relay 37, through the winding of the same, sleeve of multiple jack 36, sleeve contact of calling plug 35, alternate contact and engaged armature switch of calling super- 125 130

visory relay 50, winding of calling relay 39 and "talking" interrupter 24, completing the circuit to ground through grounded battery 15. The current thus allowed to flow 5 through the winding of calling relay 39 energizes the same, its uppermost one of the two top armature switches and its bottom one first engage their respective contacts and then spring switch 38 disengages its 10 normal contact. This disengagement opens the circuit through the winding of ringing relay 40, which thereupon releases its various armature switches which resume their normal positions. The disengagement of the 15 uppermost one of the two bottom armature switches of said relay from its alternate contact opens the circuit to the ringing interrupters by way of party line ringing keys 51 and 52 and connects non-inductive resistance 63 to the normal contact of spring switch 90 by the engagement of said armature switch with its normal contact. The lowermost one of the two bottom armature 20 switches of ringing relay 40 before becoming disengaged from spring switch 90, engages the latter with its normal contact, which by way of the bottom armature switch of calling relay 39 and its engaged contact had previously been connected to winding 25 30 of the repeating coil. Therefore current from the live pole of grounded battery 15, through said winding, is substituted, without breaking the circuit, for the same current previously delivered through interrupter 91. Non-inductive resistance 63 is also bridged across the winding of calling supervisory relay 50. As a ground connection from the upper terminal of winding 29 of the repeating coil was made by the engagement 35 with its contact of the uppermost one of the two top armature switches of calling relay 39, previous to the disengagement of spring switch 44 of ringing relay 40 from its contact, the current passing through the 40 winding of calling supervisory relay 50 is not interrupted, notwithstanding the fact that its connections have been changed.

When spring switch 38 of calling relay 39 disengaged its normal contact its engagement with its alternate contact formed a shunt circuit around the armature switch and engaged alternate contact of calling supervisory relay 50. By means of this shunt circuit a possible intermittent current 45 through the winding of calling relay 39, due to a possible intermittent engagement of said armature switch with said alternate contact, due in turn, to the intermittent current flowing through interrupter 91, is thereby avoided. If preferred, the contacts closed by the actuation of calling relay 39 are made as illustrated in Figures 17 and 19 50 in relation to the corresponding calling relays therein. In these forms the contacts are made in sequence and ringing relay 40

is not de-energized until after said shunt circuit has been first established.

The engagement of the lowermost of the two top armature switches of calling relay 39 with its contact, causes the energization 70 of called line "talking" supervisory lamp 93.

The disengagement of the top armature switch of ringing relay 40 from its two contacts, extinguishes "ringing" supervisory lamp 49 and opens the circuit through the 75 upper winding of controlling relay 23. However, as has been already mentioned, the current flowing through the lower winding of said relay maintains its armature switch disengaged from its contact. The 80 engagement of spring switch 43, of ringing relay 40, with its normal contact energizes calling line "talking" supervisory lamp 57.

As the telephone apparatus at both the calling and called sub-stations are now connected to the respective windings of the repeating coil, telephonic conversation can be held between said sub-stations.

Each sub-station has independent control 90 of its line signal and link connector apparatus. Once a telephonic connection has been established, either sub-station can disconnect itself from the one to which it is connected and instantly operate its line signal so as to obtain another connection, which 95 can be made without removing the link connector used to establish the previous connection. Also, whenever a telephone receiver is replaced upon its switch-hook at either 100 of the connected sub-stations, that line will at once test "not busy" at all the multiple jacks associated with said line. In other words the "taking down" of the connection made by means of one of the link connectors is not essential to the clearing of the lines 105 for further connections thereto.

When answering relay 25 actuated, as hereinbefore described, a circuit was closed 110 which has not been heretofore traced or described. This circuit may be traced as follows: from the live pole of grounded battery 15 through "talking" interrupter 24, uppermost one of the three bottom armature switches and engaged contact of answering relay 25, to the center terminal of the winding of said relay, through the upper portion of said winding, sleeve contact of answering plug 20, sleeve contact of answering jack 12 and winding of cut-off relay 13, completing the circuit through grounded battery 15. This circuit short-circuits the lower half of the winding of answering relay 25, which received current from interrupter 24, in the first place, through the alternate contact and armature switch of 120 answering supervisory relay 21. When the calling party at sub-station 1 replaces receiver 2 upon switch-hook 4, the circuit through the right hand winding of answering supervisory relay 21 is opened and the 125 130

armature switch of said relay disengages its alternate contact and engages its normal contact which is connected to the sleeve contact of answering plug 20. The current from 5 interrupter 24 now has two paths leading from the central terminal of the winding of answering relay 25, one towards the upper terminal of said winding and thence to said sleeve contact and one towards the bottom 10 terminal of said winding, and thence through said armature switch and normal contact of answering supervisory relay 21 to said sleeve. As these two windings are opposed to each other, relay 25 becomes de- 15 energized and its various armature switches disengage their respective contacts. (one of the objects in arranging for such a de-energization of answering relay 25 is on account of the sensitive action inherent in supervisory 20 relays which are inserted in the talking circuits. A momentary disengagement of the armature switch of answering supervisory relay 21 from its alternate contact will not release answering relay 25, due to 25 the shunt circuit around said armature switch, it being necessary for said armature switch to fall all the way back and engage its normal contact before said release can be effected.) Current is thereby cut off from 30 the tip, ring and sleeve contacts of answering plug 20 and therefore cut-off relay 13 is de-energized, its armature switches engaging their contacts thereby restoring line relay 14 and line lamp or signal 17 to the 35 control of the apparatus at sub-station 1. It will be seen, therefore, that it is immaterial whether answering plug 20 is removed or not from answering jack 12, as the three strands of the link connector are all open 40 and from an operating standpoint there is no connection from the jack to the link connector. As long as calling plug 35 remains connected to the multiple jack of the called line, controlling relay 23 remains actuated 45 thereby maintaining the circuit open from cut-off relay 13, through the left hand winding of answering supervisory relay 21 and operator's relay 22.

When the party at the called sub-station 50 replaces receiver 2 upon switch-hook 4, the circuit through the winding of calling supervisory relay 50 is opened and its armature switch disengages its alternate contact and engages its normal contact, thereby short-circuiting the winding of calling relay 39. The path for this short-circuit may be traced from the upper terminal of the winding of calling relay 39, through said armature switch and normal contact of calling 55 supervisory relay 50, to the lower terminal of winding of said calling relay 39. Due to this short-circuit (the object of which is the same as described in reference to answering supervisory relay 21) calling relay 39 is de-energized and its various armature switches 60 and spring switches resume their normal positions. The disengagement of the uppermost one of the two top armature switches of said relay opens the path to ground from winding 29 of the repeating coil, and the disengagement of the bottom one from its contact opens the circuit through winding 30 of the repeating coil. Therefore, the tip and ring contacts of calling plug 35 are disconnected from any source of current and 65 cannot be again connected thereto, until calling plug 35 has first been removed from multiple jack 36. However, the circuit hereinbefore traced through cut-off relay 37 and the lower winding of controlling relay 23, is 70 still maintained. Therefore said controlling relay continues to maintain its armature switch disengaged from its contact. As the lower winding of controlling relay 23 is of an extremely high resistance, the current 75 allowed to pass through it is not sufficient to maintain cut-off relay 37 in an actuated condition, and as the circuits through both ringing relay 40 and calling relay 39 have now been opened, the armature switches of cut-off relay 37 engage their normal contacts, 80 thereby restoring line relay 41 to the control of the sub-stations associated with it. Therefore, during an established connection by a link connector, if one or both of the connected sub-stations desires another connection, 85 it is only necessary to depress, momentarily switch-hook 4 and the link connector is instantly disconnected from the line and the corresponding line lamp or signal 17 is displayed. In the case of the called-sub-station this display might occur at an operator's position other than the one at which the first connection was established. In the case 90 of the calling sub-station the "recall" would occur at the same position where the first connection was established and it would only be necessary for the operator thereat to remove calling plug 35 from multiple jack 36. 95 in order to at once place operator's receiver 100 28 in talking relation again with the calling sub-station making the "recall.". This is brought about by the de-energization of controlling relay 23 which occurs as soon as the 105 connection between the sleeve contact of multiple jack 36 and the sleeve contact of calling plug 35 is broken.

The described connections were made to lines which tested "not busy." When the tip of calling plug 35 was applied to the sleeve of a multiple jack 36, previous to the connection being made thereto, had there been a link connector connected to another multiple jack associated with the same line and ringing current was being impressed thereon, a circuit would have been established which may be traced as follows: from ground through primary 94 of operator's induction coil, said primary being preferably of a high resistance, contact and en- 115

120

125

130

gaged lowermost armature switch of the two top ones of operator's relay 22, tip contact of calling plug 35, sleeve of multiple jack 36 of the tested line, sleeve of the multiple jack associated with said line to which is connected the link connector impressing ringing current on said line, sleeve contact of calling plug 35 of said link connector, and thence to "ringing" interrupter 45 by way 5 of the circuit which has already been traced, completing the circuit to ground through grounded battery 15. As "ringing" interrupter 45 is similar in character to the described interrupter 18, though its insulating segments are different, a direct current is furnished thereby which is not of a smooth quality or while continuous is pulsating in character. Therefore the current flowing through the described circuit fluctuates or varies and therefore primary 94 of operator's induction coil induces 10 an alternating current in secondary 32, which is heard as an audible signal in operator's receiver 28. This signal would be distinctive in character to "ringing" interrupter 45. As said secondary 32 and said receiver 28 are bridged across windings 26 and 27 of the repeating coil, this audible signal is also heard by the party at sub-station 1, 15 so that the report of the operator that the line "is being rung upon" is confirmed. In fact, such verbal report of the operator may be done away with altogether and the audible signal alone can serve as the notification 20 to the party at sub-station 1.

When the described busy test was made on the busy line, had the party at the called sub-station already responded to the calling signal and had removed the receiver 40 from its switch-hook, then calling relay 39 of the already connected link connector would have been actuated and ringing relay 40 de-energized, and the "busy test" circuit from the sleeve contact of calling plug 35 45 of said link connector would have been through the winding of calling relay 39 to ground through "talking" interrupter 24 and grounded battery 15. As this interrupter is adapted to furnish a direct current which fluctuates or varies in a distinct manner from that of "ringing" interrupter 45, the audible signals produced in receiver 28 and sub-station receiver 2 are also of a distinct character and the operator and the calling party would know that the called 50 for line was being talked upon or held for conversation. If the tested busy line had been one which initiated the call, then the circuit from the thimble of the tester multiple jack would have been to the thimble of the answering jack associated with the same line and thence through the winding 55 of answering relay 25 to ground through the same interrupter 24.

60 When the described busy test is made on

an idle line, if there is no calling plug connected to a multiple jack associated with said line, then the sleeve of the tested jack would be at the potential of the earth and primary 94 of operator's induction coil 65 would not be energized and consequently no audible signal produced in operator's receiver 28. If a calling plug was so connected to said tested line, but both ringing relay 40 and calling relay 39 had been de-energized, as has been hereinbefore described, then the sleeve of the tested jack would be at a potential above that of the earth, due to the current flowing from the live pole of grounded battery 15, through the lower, locking winding of controlling relay 23, which current flows through the sleeve contact of calling plug 35 and the thimble of the engaged multiple jack. However, due to the extremely high 70 resistance of said locking winding, the current which could flow to ground through primary 94 of operator's induction coil, when a busy test is so made is extremely small and the audible signal, if produced at all, in operator's receiver 28, would be heard as an extremely faint click. As all the "busy" signals consist of loud sustained tones, due to interrupters 24, 45 and 58, an operator has no difficulty in understanding 75 that said possible faint click does not indicate a busy line.

In both described cases of a busy line, the calling party can request a "waiting" connection if desired, and upon receiving this request the operator would at once insert calling plug 35 into multiple jack 36 and pay no more attention to the connection until the de-energization of all the supervisory lamps indicated the established 80 connection could be taken down. When calling plug 35 is inserted in a spring jack associated with a busy line the circuit through the tip and ring strands of the link connector attached to said plug are not 85 closed until the line has been released from the connection previously made to it. Said release, as has been fully described, taking place when the receiver at the busy sub-station is replaced upon its switch-hook.

As long as the circuit through the tip and ring strands attached to the calling plug is open, it will be seen that no interference can be made with the conversation going on between the tested busy line and the line to which it is connected, neither can the "waiting" party overhear any of the conversation passing between said lines.

The use of such interrupters as 24, 45 and 58 for the busy tests is disclosed in my before mentioned U. S. Patent No. 1,128,262, therefore no further description is considered necessary.

125 The prevention of interference with the talking circuit of a "busy" line when a 130

"waiting" connection is made is brought about partly by the comparatively high resistance of cut-off relays 13 and 37 and partly by the two-part windings of answering relay 25 and ringing relay 40. When calling plug 35 is inserted in a multiple jack associated with an idle line and a calling sub-station is connected to the answering plug of the same link connector, all the current which can pass through the winding of cut-off relay 37 flows through the complete winding of ringing relay 40. This current is sufficient to actuate ringing relay 40 and the engagement of the top armature switch 15 of said relay with its left hand contact, forces the spring switch associated with said contact into engagement with contact 95 which is connected to the center of said winding of ringing relay 40, thereby short circuiting 20 the upper portion of said winding. If another connection is thereafter made to another multiple jack associated with the same line, the current flowing through the high resistance winding of cut-off relay 37, has 25 two paths offered it, one through the low resistance of ringing relay 40 which has had the upper part of its winding short-circuited and the other path through the high resistance of the complete winding of ringing relay 40 associated with the link connector used for establishing the "waiting" connection. Ringing relay 40 is such that not enough current from cut-off relay 37 can flow through its complete winding to operate its various armature switches and spring switches when said winding is shunted by the low resistance path of another ringing relay 40 which has had the upper part of its winding short-circuited, 35 as described. However, enough current does pass through said complete winding to cause the top armature switch of said ringing relay 40 to engage its two contacts.

As spring switch 43, of ringing relay 40 does not disengage its normal contact, supervisory lamp 57 remains energized and as spring switch 42 does not disengage its normal contact, the current which flows through the upper winding of controlling relay 23 50 and the complete winding of ringing relay 40 emanates from "waiting" interrupter 58, instead of "ringing" interrupter 45 as would have been the case had ringing relay 40 fully actuated. As "waiting" interrupter 58 furnishes a fluctuating or variable current of different character to either "ringing" interrupter 45 or "talking" interrupter 24, any further busy tests made on the line will furnish an audible busy signal distinctive to the "waiting" condition and therefore no further connections would be made to said busy line.

Controlling relay 23 is also energized by the current passing through its upper winding when ringing relay 40 is in its "wait-

ing" condition, therefore the operator's telephone set is disconnected from the link connector as hereinbefore described. Also said relay remains actuated by means of the current flowing through its lower winding, 70 notwithstanding the fact that another link connector in the "waiting" condition may be associated with the same line.

When the called sub-station responds to its calling signal, calling relay 39 is actuated 75 before the circuit through ringing relay 40 is opened and as the resistance of the winding of said answering relay 39 is the same as the lower part of the winding of ringing relay 40; the ringing relay 40 associated with the link connector in the "waiting" condition does not receive an increase of current and therefore the remainder of its armature switches and spring switches do not operate. However, when the receiver of the 80 called sub-station is replaced upon its switch-hook, then the circuit for the current from the winding of cut-off relay 37 to calling relay 39 is opened and the full force of the current allowed to pass through the 85 winding of said cut-off relay 37 now passes through the complete winding of ringing relay 40 associated with the link connector in the "waiting" condition. The remaining armature switches and spring switches of 90 said relay thereupon engage or disengage their respective contacts. The engagement with contact 95 of the spring switch associated with the left hand contact of the top armature switch, in turn, short-circuits the 95 upper portion of the winding of said ringing relay, so that any further connections made to the same line will be placed in the "waiting" condition. The described delayed action of ringing relay 40 impresses ringing current on the formerly busy line in the same manner as has been fully described. If the call had been for a different sub-station than the one in use on the busy line, the correct 100 ringing current would be transmitted as operating current for magnetic clutch 46 105 would have been furnished through supervisory lamps 49 and 57 and the correct ringing key or keys would have been depressed before or after the "waiting" connection was made.

When the described "waiting" connection was made, if calling relay 39 of the busy link connector had already actuated, the same results would be brought about in regard to the "waiting" link connector, due 110 to the fact, as hereinbefore mentioned, that the resistance of said relay is that of the lower part of the winding of ringing relay 40, therefore ringing relay 40 of the "waiting" link connector is still shunted by a low 115 resistance path.

When the described "waiting" connection was made, if the tested line had been one that had initiated the call then the circuit from the cut-off relay would have been 120 125 130

through answering relay 25, instead of ringing relay 40 or calling relay 39. Answering relay 25 has a winding exactly similar to that of ringing relay 40, one-half of its winding having been short-circuited by the engagement of the uppermost one of the three bottom armature switches with its contact, as has been described. Therefore, the same results are accomplished when a 10 "waiting" connection is made to the line associated with said answering relay.

It will be seen that the described "waiting" connection would be brought about, should an operator carelessly connect a calling sub-station to a busy line, without having been requested so to do. Therefore I furnish means whereby it is impossible to telephonically connect three lines together and therefore I evade the confusion which 20 now arises when, by accident, a third party is connected to a busy line.

Due to the two part winding of answering relay 25, it is also impossible for an operator to connect her telephone set to a busy 25 line or otherwise make a connection thereto by means of the answering plug. When answering plug 20 is inserted in a jack a circuit has been traced through the left hand winding of answering supervisory relay 21, which 30 is energized by the current flowing therethrough, and another circuit has been traced through the armature switch and engaged alternate contact of said relay, said circuit including the complete winding of answering 35 relay 25. Therefore if the current allowed to pass through the high resistance winding of cut-off relay 18 has an alternative path through the low resistance of another answering relay 25 which has had the lower part of its winding short circuited by 40 its actuation, as has been described, this low resistance shunt is sufficient to prevent enough current flowing through the high resistance path offered by the complete winding 45 of the first mentioned answering relay 25, to actuate the same. As the tip and ring strand circuits connected to the answering plug remain open until answering relay 25 has actuated it will be seen that no interruption 50 to a conversation can be brought about by the connection to a busy line of an answering plug and that an operator cannot thereby connect her telephone set to said busy line.

From the description so far given, it will be seen that it is impossible for an operator to listen to a conversation passing through a link connector, as controlling relay 23 is actuated as soon as a connection is made by means of 60 calling plug 35 and therefore the circuit through operator's relay 22 is opened, preventing thereby the association of operator's receiver 28 with said link connector. Therefore, the talking or listening capacity 65 of an operator is strictly limited to answer-

ing calls initiated at calling sub-stations and neither said operator nor another party at a sub-station can interfere in any way with a conversation passing between two connected sub-stations.

Another unique feature of my present invention relates to the arrangement of the supervisory lamps, associated with the respective link connectors. As it is one of the purposes of this invention to allow link connectors to remain engaged with the jacks associated with the telephone lines after the completion of the conversations between connected sub-stations and until the 70 duties of the operator give an opportunity or make it convenient to remove them, the usual operation of the supervisory signals, for the sake of economy in consumption of current, has been reversed and the supervisory lamps are energized while the sub-stations are busy and are extinguished when the respective receivers are placed upon their switch-hooks. As the system hereinbefore described includes automatic ringing and automatic "waiting," it also includes 75 supervisory signals distinctive to these operations as well as distinctive to the "talking" condition of the link connector. In order to simplify these signals, reduce the 80 number of lamps used and to curtail the supervisory work entailed on an operator by the observation of a plurality of supervisory lamps, I use but three lamps for this purpose and by the energization of one or 85 more of the same I am enabled to obtain 90 five distinct signals. To still further reduce the supervisory work of the operator, the preferred way of mounting the three 95 supervisory lamps is as shown diagrammatically in Figure 1, where the three lamps are shown close together and mounted under one transparent or semi-transparent cap 96, so that in operation the effect is the same 100 as if but one lamp was used. In other words, the operator has to observe what 105 would correspond ordinarily to but one lamp. To obtain the five mentioned supervisory signals the three lamps are of different colors, and while I do not wish to be 110 limited to any particular color combination (as there are many such) I have found the following very satisfactory, to wit: red for lamp 57, which is controlled by answering relay 25; yellow for lamp 49, which is controlled by ringing relay 40; and blue for 115 lamp 93, which is controlled by calling relay 39.

When answering plug 20 is inserted in a jack and answering relay 25 has actuated, a red light is therefore shown through cap 96. This color, whenever displayed, indicates that the calling party is still connected to the link connector and that no other connection is made therewith.

When calling plug 35 of the same link 120

connector is inserted in a jack of a busy line, then lamp 49 (controlled by the top armature switch of ringing relay 40) is also energized, lamp 57 remaining energized 5 owing to the fact that spring switch 43 of ringing relay 40 has not disengaged its normal contact. The effect of the red and yellow lamps both being energized is to show an orange light through cap 96. This color, 10 whenever displayed, indicates that the calling party is "waiting" on a busy line.

When calling plug 35 of the same link connector is inserted in the jack of an idle line, then lamp 57 is extinguished by means 15 of spring switch 43 of ringing relay 40 disengaging its normal contact, therefore lamp 49 alone remains energized and shows a yellow light through cap 96. This color, whenever displayed, indicates that the called 20 for line is being rung upon.

When the called for party responds and calling relay 39 has actuated, lamp 93 is energized, lamp 49 is extinguished and lamp 57 is again energized by the de-energization 25 of ringing relay 40. The effect of the red and blue lamps both being energized is to show a purple light through cap 96. This color, whenever displayed, indicates that the calling and called parties are conversing 30 or are holding the connection for conversational purposes.

When a calling party replaces the receiver upon its switch-hook and the called party does not do the same, then the consequent extinguishing of lamp 57 causes a blue light to be shown under cap 96. This color, whenever displayed indicates that the called party is still connected to the link connector and that the calling party is 35 disconnected thereto. As all three of the lamps are mounted in series with the winding of magnetic clutch 46 the resistance of the same diminishes the intensity of the lamps when two are burning so that the lamps when two are burning so that the light produced by the two lamps is practically the same as that produced by one. When party line ringing keys are not used 40 a resistance may be substituted for said winding. Instead of mounting the lamps as shown and described, they can be all of one color and mounted separately, in which event the signals would be according to those energized.

In practice an operator would pay no 45 attention to any one of the described supervisory signals unless one such was displayed for an inordinate time, when the matter would be investigated by said operator or another official and any desired action taken. For instance, the continued display of the 50 color yellow would indicate that the called for party had not answered and the calling party would be notified accordingly. The continued display of the color orange would 55 indicate that the "waiting" connection was

made to a line over which a very long conversation was being held, or that the receiver at the desired sub-station had been left off its switch-hook, and the calling party could be notified accordingly and the link connector thereby released for other connections. The continued display of the color red or blue would indicate that the calling or called party had left the respective receiver off its switch-hook and action could be taken accordingly. 70 75

Whenever an operator is not engaged in establishing connections, providing there are already connections established, said operator observes the supervisory signals, and 80 for the sake of convenience, takes down those link connectors which do not display any supervisory signal.

However, should an operator be confronted by a shortage of link connectors the connections which displayed red or blue lights could be taken down and the link connectors used for establishing new connections. Also, 85 if any link connector displayed an orange light it could be disconnected from the called 90 line and connected to a special operator who would inform the "waiting" party that the called party had not yet released his line and that the "waiting" party would be called 95 as soon as the line was available. In this manner the release of the link connector 95 would be obtained.

The connection from the lower terminal of the lower winding of controlling relay 23 and from the normal contact of said 100 relay, is shown as made to the live pole of grounded battery 15. If preferred this connection could be made to the corresponding pole of another grounded battery and the action of both operator's relay 22 and controlling relay 23 made more sensitive thereby, as the respective windings would not be shunted by other circuits. 105

Many other changes and modifications of the described circuits may be made without departing from the spirit and scope of the 110 invention.

It will be noted that the tip and ring strand circuits of the calling link connector do not pass through all the various party 115 line ringing keys in series, as is the case in other party line ringing systems in general use, but that said circuits only pass through reversing keys 53 and 54. This I claim is 120 a distinct advantage as much trouble is experienced with the old style ringing keys due to the increased resistance in the talking circuit due to the multiplicity of contacts in the party line ringing keys which the 125 talking circuit traversed. Also if one of said contacts should become loose the talking efficiency of the associate link connector is impaired or destroyed.

I have shown in Figure 2 how reversing 130 keys 53 and 54 can be done away with, by

substituting two calling link connectors and plugs connected together with reversed terminals, one or the other of said plugs and connectors being used according to the desired sub-station on a party line. By using such a combination of cords, the party line ringing keys can be greatly simplified and the talking circuit of the link connectors would not traverse any key contacts.

10 Release key 48 of magnetic clutch 46 is provided so that in case an operator depresses or manipulates the wrong ringing key, the same can be released. Normally the depressed or manipulated ringing keys are

15 not released until the parties at both the calling and called sub-stations have replaced their respective telephone receivers on their switch-hooks, thereby opening the circuits through the supervisory lamps and 20 consequently opening the circuit through the winding of magnetic clutch 46.

Should the calling party at sub-station 1, replace his telephone receiver upon its switch-hook, previous to the response of the 25 called party, the ringing current is at once cut off from the called sub-station, and the called line is freed for further connections. This action is brought about by the fact that 30 operating current for ringing relay 40 is furnished through the lowermost of the two top armature switches of answering relay 25, in the case of a "waiting" connection, or through the intermediate one of the three 35 bottom armature switches of said relay, in the case of a "ringing" connection. In either case, the de-energization of answering relay 25, due to the replacing of receiver 2 on switch-hook 4 at sub-station 1, would open the circuit through ringing relay 40 40 which would consequently release its various operated armature and spring switches. As no operating current would therefore be passing through cut-off relay 37, the same would also be de-energized and line relay 41 would 45 be restored to the control of the sub-stations associated with it.

I have shown at Figure 3 an alternative form of producing the required alternating ringing current for party lines, consisting of strong current of one polarity and weak current of the other polarity. Interrupters 50 97 and 98 are counterparts of interrupters 60 and 70. However, they are both connected to one terminal of ringing generator 59, the other terminal being connected to ground.

Brush 99 engages the center of the exposed metallic portion of interrupter 97, when the positive current delivered to said 60 interrupter by generator 59 is at its maximum. Brush 100 engages the center of the exposed metallic portion of interrupter 98, when the negative current delivered to said interrupter by generator 59 is at its maximum. A suitable resistance 101 connects the

two brushes, therefore if brush 99 is connected to a sub-station line, the positive alternation will be that of generator 59, while the negative alternation will be according to the current allowed to pass through resistance 101. If brush 100 was connected to a 70 substation line then the negative alternation would be that of generator 59 and the positive alternation according to the current allowed to pass through said resistance 101. It will be seen that the biased bells can be 75 operated by such a combination instead of the one disclosed in Figure 1, and described hereinbefore.

In Figure 4 I have illustrated a modification of the system illustrated in Figure 1. In this form, when answering plug 102 (Figure 4) is inserted in the answering jack, a circuit is closed which may be traced as follows: from ground through the winding of cut-off relay 13, (Figure 1) sleeve of answering jack 12, sleeve contact of answering plug 102 (Figure 4), left hand winding of answering supervisory relay 103, normal contact and spring switch 104 of answering relay 105, top armature switch and left hand normal contact of controlling relay 106, retardation coil 107 and grounded battery 108, completing the circuit to ground. Retardation coil 107 is of a comparatively high resistance, but allows enough current to pass to actuate answering supervisory relay 103. The actuation of said relay closes another circuit which may be traced as follows: from ground, through cut-off relay 13, (Figure 1) sleeve of answering jack 12, sleeve of answering plug 102 (Figure 4), contact and engaged armature switch of answering supervisory relay 103, winding of answering relay 105 and grounded battery 108, completing the circuit to ground. Cut-off relay 13 (Figure 1) is actuated by the current flowing through this circuit and removes line relay 14 from connection with the calling sub-station line, as has hereinbefore 100 been described. The actuation of answering relay 105 closes a circuit; which may be traced as follows: from ground, through winding 109 of the repeating coil, spring switch 110 and engaged top armature switch of answering relay 105, ring contact of answering plug 102, ring spring contact of answering jack 12 (Figure 1), sub-station apparatus of the calling line (as has been hereinbefore described), tip spring contact of answering jack 12, tip contact of answering plug 102, (Figure 4) right hand winding of answering supervisory relay 103 and the non-inductive resistance in multiple relation therewith, winding 111 of the repeating coil, left and right hand contacts and engaged bottom armature switch of answering relay 105, and grounded battery 108, completing the circuit to ground. After having established this circuit, 130

5 spring switch 110 engages spring switch 104 of answering relay 105 and disengages the same from its normal contact, thereby opening the circuit through the left hand winding of answering supervisory relay 103. However, the armature switch of said relay does not disengage its contact, owing to the current flowing through the right hand winding of the same.

10 The actuation of answering relay 105 also connects the operator's telephone set to the calling line. A circuit for this connection may be traced as follows: from the ring strand of the link connector through engaged spring switches 110 and 104 of answering relay 105, left hand normal contact and top armature switch of controlling relay 106, secondary 113 of operator's induction coil, receiver 114, condenser 112, bottom armature switch and left hand normal contact of controlling relay 106, where connection is made to the tip strand of the link connector. By means of this circuit the operator and the calling party can converse together.

15 25 A circuit in branch relation to the described one may be traced from ground through winding 109 of the repeating coil, top armature switch and engaged spring switches 110 and 104 of answering relay 105, left hand normal contact and top armature switch of controlling relay 106, retardation coil 107 and grounded battery 108, completing the circuit to ground. Notwithstanding the shunt circuit so formed, on account of 30 35 the high resistance of this retardation coil, there is sufficient current to operate the sub-station telephone apparatus and energize the right hand winding of answering relay 103. Also, on account of the high impedance of 40 45 said retardation coil the voice currents passing between the sub-station telephone receiver and that of the operator, are not affected.

Having been told the number of the calling party desires to be connected with, the operator tests the called for line in the same manner as has been hereinbefore described. If the line is busy a circuit for the busy test may be traced as follows: from tip contact 45 50 of calling plug 115, winding 116 of the repeating coil, right and left hand contacts of the top armature switch of controlling relay 106, spring switches 104 and 110 and top armature switch of answering relay 105, winding 109 of the repeating coil to ground. If 55 60 the sleeve of the tested jack is of a potential above that of the earth, current flows through the special test winding 116 of the repeating coil and as the same is in inductive relation to winding 109, the latter is affected not only directly by said current but also inductively. Therefore a busy signal is heard in the sub-station receiver and that of the operator. The busy signal may or may not be 65 70 of the character as described in relation to

Figure 1, according to whether the described interrupters 24, 45 and 58 are used or not.

When calling plug 115 is inserted in a multiple jack of a called for line, a circuit is closed which may be traced as follows: 70 from ground through the winding of cut-off relay 37, (Figure 1) sleeve of multiple jack 36, sleeve contact of calling plug 115 (Figure 4), winding of ringing relay 116', right and left hand contacts of the bottom armature switch of controlling relay 106, winding 111 of the repeating coil, left and right hand engaged contacts of the bottom armature switch of answering relay 105 and grounded battery 108, completing the circuit 75 to ground. Due to the current flowing through this circuit, the cut-off relay is actuated, as hereinbefore described, and ringing relay 116' is also actuated. The engagement with its contact of the uppermost one of the two top armature switches of said relay, connecting the ring strand of the link connector to ground through winding 117 of the repeating coil. The engagement of the lowermost one of the two top armature switches 80 of said relay with its contact, closes a circuit to the live pole of grounded battery 108, in branch relation to the one from the winding of said relay through winding 111 of the repeating coil. This branch circuit may be 85 traced as follows: from the upper terminal of said winding, lowermost one of the two top armature switches of said relay and its engaged contact, upper winding of controlling relay 106, normal contact and uppermost one of the two bottom spring switches 90 of calling relay 118, bottom armature switch and engaged right hand contact of answering relay 105, to the live pole of grounded battery 108. Due to the current flowing 95 through this circuit, controlling relay 106 is actuated and its armature switches disengage their respective contacts, thereby removing the operator's telephone set from association with the link connector, opening 100 the busy test connection to the tip of calling plug 115 and also opening the connection from the upper terminal of the winding of ringing relay 116', through winding 111 of the repeating coil to the live pole of grounded battery 108. As the described circuit through the upper winding of controlling relay 106 was closed before this circuit was 105 opened, ringing relay 116' remains energized.

110 The operation of the two bottom armature switches of ringing relay 116' impresses ringing current on the called for line in the same manner as has been hereinbefore described, line 119 leading to the proper ringing key, if party line ringing keys are used, or direct to the proper ringing interrupter. Line 120 leading to the brush of battery interrupter 91 (Figure 1).

125 130 The energization of calling relay 118 when

- the called party responds, takes place, as has been hereinbefore fully described, excepting that the circuit closed by the armature switch of calling supervisory relay 121 is different. This circuit may be traced as follows: from ground through cut-off relay 37, (Figure 1) sleeve of multiple jack 36, sleeve of calling plug 115, (Figure 4) winding of calling relay 118, armature switch and alternate contact of calling supervisory relay 121, and grounded battery 108, completing the circuit. The top armature switch of calling relay 118 closes the ring strand of the link connector to ground through winding 117 of the repeating coil; the uppermost of the two bottom spring switches of said relay disengages its normal contact, after the top and bottom armature switches have engaged their contacts. Therefore when said spring switch disengages its normal contact thereby opening the circuit through the upper winding of controlling relay 106 and winding of ringing relay 116', de-energizing the latter, the circuit through calling supervisory relay 121 remains unbroken. A shunt circuit is established around the armature switch and alternate contact of calling supervisory relay 121 by the engagement of the uppermost one of the two bottom spring switches of calling relay 118 with its alternate contact. This circuit may be traced as follows: from the lower terminal of the winding of calling relay 118 through said alternate contact and spring switch, right hand contact and engaged bottom armature switch of answering relay 105 to the live pole of grounded battery 108. The purpose of this shunt circuit is the same as has been hereinbefore described in relation to the same relay in Figure 1.
- 40 A circuit is also closed through supervisory lamp or signal 121' by the operation of said spring switch. This circuit may be traced as follows: from ground through supervisory lamp or signal 121', uppermost one of the two bottom spring switches and engaged alternate contact of calling relay 118, armature switch and engaged alternate contact of calling supervisory relay 121 and grounded battery 108, completing the circuit to ground. Another circuit through supervisory lamp or signal 121' may be traced as follows: from ground through said lamp or signal, right hand engaged contact and bottom armature switch of answering relay 105, and grounded battery 108, completing the circuit. It will therefore be seen that supervisory lamp or signal 121' is displayed if either answering relay 105 or calling relay 118, or both, are energized. As illustrated 60 only one supervisory lamp or signal is used and the operator does not take down the connection as long as such display continues.
- Should the calling party replace his receiver upon its switch-hook before the called party responded, the consequent disengagement of the armature switch of answering supervisory relay 103 from its contact would open the circuit through answering relay 105, which would not only open the tip and ring strands connected to the answering plug but would open the circuit from the live pole of grounded battery 108, by way of the uppermost spring switch and normal contact of the two bottom ones of calling relay 118, which energizes the upper winding of controlling relay 106 and ringing relay 116'. Therefore ringing relay 116' would be de-energized, ringing current cease to be impressed upon the called line and the latter automatically restored to its normal idle condition.
- Controlling relay 106 would not be de-energized by the opening of said circuit as current flows through the lower, locking winding thereof as long as calling plug 115 is connected to a multiple jack. A circuit for this current may be traced as follows: from ground through cut-off relay 37, (Figure 1) sleeve of multiple jack 36, sleeve contact of calling plug 115, (Figure 4) said lower winding of controlling relay 106 and grounded battery 108, completing the circuit to ground.
- As said lower winding is of a high resistance cut-off relay 37 does not receive sufficient current to maintain its actuation.
- When the calling party replaces his receiver upon its switch-hook after the calling party was responded, the same procedure takes place, excepting that ringing relay 116' would have been previously de-energized by the response of said called party.
- When the called party replaces his receiver upon its switch-hook, calling supervisory relay 121 is de-energized, as has been hereinbefore described in relation to Figure 1, and its armature switch engaging its alternate contact short circuits the winding of calling relay 118, thereby causing the de-energization of the same and the consequent return of its various armature switches to their normal condition. A circuit for this short-circuit may be traced as follows: from the upper terminal of the winding of calling relay 118 through the normal contact and armature switch of calling supervisory relay 121 to the lower terminal of said winding. The object of arranging for this short-circuit is the same as that mentioned in relation to the supervisory relays illustrated in Figure 1.
- As the de-energization of calling relay 118 opened the tip and ring strands connected to calling plug 115, cut-off relay 37, (Figure 1) is deenergized and the called line automatically restored to its normal idle condition.
- In Figure 5 I have illustrated a still further modification of the same system. As the essential features are the same as those

already amply described, mention will here be made only of those features which are distinct in character from the beforementioned ones.

- 5 When answering plug 122 is inserted in the answering jack of the calling line, a circuit is closed which may be traced as follows: from ground through cut-off relay 13 and sleeve of answering jack 12, (Figure 1) sleeve contact of answering plug 122, (Figure 5) lower winding of answering relay 123, winding of operator's relay 124, armature switch and normal contact of controlling relay 125, resistance 126 and 70 grounded battery 127, completing the circuit to ground. Cut-off relay 13, answering relay 123, and operator's relay 124 are actuated by the current flowing through this circuit. The engagement of the uppermost one of the two top armature switches 75 of answering relay 123 with its contact closes the circuit through the ring strand of the link connector to ground through winding 128 of the repeating coil and the engagement of the lowermost one of the two bottom armature switches with spring switch 129 closes the circuit through the tip strand, including the winding of answering supervisory relay 130, to the live 80 pole of grounded battery 127 through winding 131 of the repeating coil. Said armature switch after having established said connection engages spring switch 129 with its contact, thereby bridging non-inductive 85 resistance 132 around the winding of answering supervisory relay 130, after said relay has been energized by the current allowed to flow through its winding previous to the establishment of the bridge. In this 90 way a more efficient operation of the supervisory relay is obtained than if non-inductive resistance 132 was permanently bridged across said winding. The engagement with its contact of the lowermost one of the two 95 top armature switches of answering relay 123 closes a circuit which may be traced as follows: from ground through the winding of cut-off relay 13 and sleeve of answering jack 12, (Figure 1) sleeve contact of answering plug 122, (Figure 5) said contact and armature switch, upper winding of answering relay 123 and grounded battery 127, completing the circuit to ground. This 100 winding is energized by the current flowing therethrough as the short-circuit around the same closed by the armature switch of answering supervisory relay 130 and its contact has been opened by the described energization of said supervisory relay. The engagement with its contact of the uppermost 105 of the two bottom armature switches of answering relay 123, closes a circuit which may be traced as follows: from ground through the winding of magnetic clutch 133 of party line ringing key 134, answering 110
- supervisory lamp or signal 135, said armature switch and contact and grounded battery 127, completing the circuit to ground. Answering supervisory lamp 135 is displayed thereby and will remain displayed until answering relay 123 is de-energized. The energization of operator's relay 124 115 telephonically connects the operator's telephone set to the substation telephone set. A circuit for this connection may be traced as follows: from ground through winding 128 of the repeating coil, uppermost of the three top armature switches and engaged contact of said relay, operator's receiver 136, secondary of operator's induction coil 120 137, condenser 138, engaged left and right hand contacts of the lowermost of the three top armature switches of said relay and winding 131 of the repeating coil, thereby placing said set in inductive relation with 130 the sub-station telephone set.
- When a busy test is made on a called for line the tip contact of calling plug 139 is connected to primary 140 of operator's induction coil by way of the middle one of the three top armature switches and its engaged contact of operator's relay 124. When calling plug 139 is inserted in a multiple jack of a called for line, a circuit is closed which may be traced as follows: from ground through cut-off relay 137 and sleeve of multiple jack 36, (Figure 1) sleeve contact of calling plug 139, (Figure 5) spring switch 141 and normal contact of calling relay 142, winding of ringing relay 143, right hand contact and engaged lowermost one of the three top armature switches of operator's relay 124, winding 131 of the repeating coil and grounded battery 127, completing the circuit to ground. Cut-off relay 105 137 and ringing relay 143 are both actuated by the current flowing in this circuit. The actuation of the latter closing a circuit in branch relation to the last described circuit which may be traced as follows: from the uppermost of the two bottom armature switches of answering relay 123, lower winding of controlling relay 125, lowermost of the two top armature switches of ringing relay 143 and its two engaged contacts, ringing supervisory lamp or signal 144 to ground 110 and winding of ringing relay 143 as already traced.
- Ringing supervisory lamp or signal 144 is displayed, due to the current flowing 120 through this circuit and controlling relay 125 is actuated by the same. Operator's relay 124 is not at once de-energized by the disengagement of the armature switch of controlling relay 125 from its normal contact, owing to the fact that said armature switch and contact were shunted by the engagement with its contact of the uppermost of the three bottom armature switches of operator's relay 124. Controlling relay 125 125 130

may be of a slow-acting type and when its armature switch engages its alternate contact a circuit is closed which may be traced as follows: from ground through the 5 ready traced circuit to the armature switch of controlling relay 125, its alternate contact, middle one of the three bottom armature switches and engaged contact of operator's relay 124, winding of disconnect relay 145 and grounded battery 127, completing the circuit to ground. Disconnect relay 145 is preferably also of a slow-acting type so that the current flowing through said circuit does not at once cause its armature switch to engage its contact. When it does so, however, the circuit through operator's relay 124 from resistance 126 is short-circuited and consequently said relay is de-energized and its various armature 15 switches resume their normal condition. Disconnect relay 145, which is common to all the link connectors at an operator's position, is de-energized when operator's relay 124 is de-energized and its armature switch 20 disengages its contact. When the uppermost of the three bottom armature switches of operator's relay 124 disengaged its contact the circuit through the winding of said relay and the lower winding of an 25 answering relay 123 was opened and cannot again be closed until calling plug 139 is disengaged from the multiple jack with which it is connected, as the current flowing through the upper locking winding of controlling relay 125, as hereinbefore described 30 in relation to controlling relay 23 in Figure 1, is sufficient to maintain its armature switch disengaged from its normal contact.

Answering relay 123 has not been de-energized during the just described operations, due to the current flowing in the upper winding thereof.

Ringing current is now impressed upon the called for line, a circuit for which may be traced as follows: from ground through winding 146 of the repeating coil, uppermost one of the two top armature switches and engaged contact of ringing relay 143, ring contact of calling plug 139, called substation call-bell or annunciator, (as described in relation to Figure 1) tip contact of calling plug 139, non-inductive resistance 147, winding 148 of the repeating coil, uppermost one of the two bottom armature switches and alternate contact of ringing relay 143, lowermost one of the three bottom armature switches and alternate contact of operator's relay 124, (which has not yet been de-energized, due to the described slow action of controlling relay 125, and operator's disconnect relay 145), bottom spring switch and normal contact of the left hand key of party line ringing key 134, bottom spring switch and normal contact of the right hand key of the same, "con-

stant ringing interrupter" 149 and alternating current ringing generator 150, completing the circuit to ground. As "constant ringing interrupter" 149 furnishes ringing current which is not periodic, a calling signal is sounded on the call bell at the called sub-station the instant ringing relay 143 actuated and as said ringing current traverses winding 148 of the repeating coil, both the operator and the calling party receive an audible signal in their respective telephone receivers, due to their connection to windings 128 and 131 of said repeating coils.

The continuous ringing current from interrupter 149 continues to be impressed upon the called for line until the described actuation of slow-acting controlling relay 125 and slow-acting disconnect relay 145 has taken place, whereupon the de-energization of operator's relay 124 causes the lowermost one of the three bottom armature switches of said relay to disengage its alternate contact and engage its normal contact. Therefore, the ringing circuit is changed and now passes through said normal contact, top spring switch of the left hand key and normal contact of party line ringing key 134, top spring switch of the right hand key and normal contact of the same, "periodic ringing interrupter" 151, "constant ringing interrupter" 149 and alternating current ringing generator 150, completing the circuit to ground. "Periodic ringing interrupter" 151 revolves slowly and furnishes long silent intervals between rings at the sub-stations, hence the described arrangement whereby a ring at a called sub-station is produced without any delay when calling plug 139 is inserted in a multiple jack.

The two party line system illustrated in Figure 5, is one wherein but two sub-stations are connected to a line, the biased call bells being connected direct from the tip limb of the line to ground. Such an arrangement is well known in the art. However, it will readily be seen that the ringing system so far disclosed with reference to Figure 5, is applicable to that disclosed in relation to Figures 1 and 4.

If the call had been for a party line sub-station which required positive pulsating current to be delivered to the tip side of the line, then the left hand key of party line ringing key 134 would have been depressed or manipulated previous to inserting calling plug 139 in the multiple jack of the called line. Said key is retained in its depressed or manipulated position by magnetic clutch 133 which has been energized, as hereinbefore described. The continuous ringing circuit connection would then have been through the alternate contact of the bottom spring switch of said key, brush 152 of "pulsating current constant ringing interrupter" 153 and alternating current ring-

130

ing generator 150, completing the circuit to ground. "Pulsating current constant ringing interrupter" 153 is a counterpart of interrupter 60, which was fully described in relation to Figure 1. The periodic ringing circuit connection made at the same time as the continuous ringing circuit connection, would then have been through the alternate contact of the top spring switch of said key, "positive pulsating current periodic ringing interrupter" 154 to brush 152. Interrupters 154 and 155 are counterparts of interrupter 151 and preferably revolve at the same speed and preferably have their exposed metallic portions so arranged that current from ringing generator 150 passes successively through each of them, thereby distributing the load on said ringing generator.

If the called sub-station required negative pulsating current to be delivered to the tip side of the line, then the right hand key of party line ringing key 134 would have been depressed or manipulated. This would have changed the ringing circuit connections to brush 156 of interrupter 153 and negative pulsating current periodic ringing interrupter 155.

In the case of the alternating current ringing, which would be to call bells as shown at sub-station 1 in Figure 1, the ringing current returned to ground through winding 146 of the repeating coil. Therefore the described audible signal in the calling party's receiver and that of the operator would have been produced by the inductive effect of the ringing current passing through both windings 148 and 146 of said repeating coil. However, when the described party line ringing is used, the ringing current returns to ground at the sub-station bell, therefore said audible signal is produced by the inductive effect of winding 148, of said repeating coil, alone. This would produce an audible signal not as loud as that produced by the traversing of both windings by the ringing current and this difference in strength would indicate whether the party line key had been actuated or not. Calling supervisory relay 157 is not actuated due to the circuit through the grounded connection of the sub-station bells on account of the high resistance of the latter, however, it actuates when a lower resistance path to ground through winding 146 of the repeating coil is furnished when the called sub-station receiver is removed from its switch-hook. To still further insure its non-operation when the circuit is closed through said call bell, battery interrupter 160 may be connected to the live pole of a grounded battery of much less voltage than the one to which the repeating coil is connected.

When the called party responds, the actuation of calling supervisory relay 157, and

the consequent actuation of calling relay 142 causes its bottom armature switch to engage spring switch 158, before spring switch 141 is disengaged from its normal contact, thereby opening the circuit through ringing relay 143. The consequent return to normal position of the armature switches of ringing relay 143 takes place as follows: The uppermost of the two bottom armature switches engages its normal contact before the lowermost one disengages spring switch 159; therefore when said disengagement takes place, winding 148 of the repeating coil is already connected to the live pole of grounded battery 127, so that when switch spring 159 engages its normal contact there is no interruption to the current flowing through the winding of calling supervisory relay 157, as the connection from said winding is changed without a break from "battery interrupter" 160 through the lowermost of the two bottom armature switches of ringing relay 143, to a connection to the live pole of grounded battery 127 through winding 148 of the repeating coil, spring switch 158 and engaged armature switch of calling relay 142 and normal contact of spring switch 159 of ringing relay 143.

The engagement of the uppermost one of the two top armature switches of calling relay 142 with its contact connected the ring strands of the link connector to ground through repeating coil winding 146, previous to the disconnection of the same from said winding by the disengagement from its contact of the uppermost one of the two top armature switches of ringing relay 143.

The disengagement from its two contacts of the lowermost one of the two top armature switches of ringing relay 143, extinguishes ringing supervisory lamp or signal 144 and prevents the re-energization of ringing relay 143 during an established connection. Finally, the engagement with its contact of the lowermost one of the two top armature switches of calling relay 142, displays calling supervisory lamp or signal 161.

Should the calling party replace the sub-station receiver upon its switch-hook, previous to the response of the called party, the circuit is opened through ringing relay 143, by the disengagement from its contact of the uppermost of the two bottom armature switches of answering relay 123. Therefore ringing current is cut off from the called line and the same is automatically restored to its normal idle condition.

In Figure 6, I have shown an alternative method of obtaining the de-energization of operator's relay 124 (Figure 5) and the prevention of its re-energization during an established telephonic connection between two substations. This method eliminates

entirely the use of controlling relay 125 (Figure 5). In said Figure 6 I have not illustrated anything but said alternative method of control of the operator's relay, it being understood that the other functions, contacts, etc., are the same as shown in Figure 5. Referring to Figure 6; when answering plug 122 is inserted in the answering jack of the calling line, current 10 flows from ground through the sleeve contact of said plug, lower winding of answering relay 123, winding of operator's relay 124, plug seat switch 162 and normal contact, normal contact and lowermost of the 15 two top armature switches of calling relay 142 and grounded battery 127, completing the circuit to ground. The current flowing through this circuit actuates answering relay 123 and operator's relay 124. The engagement with its contact of the uppermost of the two bottom armature switches of operator's relay 124 establishes another path to grounded battery 127, through resistance 126 so that when calling plug 139 is removed 20 from plug seat switch 162, thereby disengaging the latter from its contact, operator's relay 124 is not de-energized. When calling plug 139 is inserted in the multiple jack of the called for line a circuit is established from ground through the sleeve contact of said plug, lowermost one of the 25 two bottom armature switches of operator's relay 124 and engaged contact, winding of disconnect relay 145 and grounded battery 127, completing the circuit to ground. Disconnect relay 145 being of a slow-acting type allows time for the first ringing signal to be impressed upon the called for line and for the operator to hear the same, in the 30 manner hereinbefore described, and then engaging its contact, short-circuits the winding of operator's relay 124 and consequently causing the disengagement of its armature switches, which thereupon open the circuits 35 controlled by them. It will be seen that operator's relay 124 cannot be again energized until plug seat switch 162 has engaged its contact. Said plug seat switch is preferably so arranged that a button 163 40 projects above the key shelf of the switchboard when calling plug 139 is not in its seat. By depressing this button operator's relay 124 can be initially energized manually, should calling plug 139 not be in its seat when a connection is to be made to answering plug 122. It will be observed that when calling relay 142 actuates, the lowermost of the two top armature switches of 45 said relay disconnects the normal contact of plug seat switch 162 from grounded battery 127, therefore operator's relay 124 cannot be energized again while the called substation is telephonically connected with the calling sub-station. By this means inter-

ference is obviated and it is impossible for 65 an operator to listen to the conversation passing through the associate link connector.

In Figure 7 I have illustrated a different system of supervision. As this system may 70 be used with any of the forms illustrated in the preceding figures I have only shown the relay connections involved in said system of supervision, it being understood that the connections involved in establishing, maintaining and disconnecting a telephone connection are as illustrated in the preceding figures and as described hereinbefore.

When answering relay 164 and controlling relay 165 actuate, two circuits are closed 80 which may be traced as follows: from ground through supervisory lamp or signal 166, left hand contact and engaged uppermost one of the two bottom armature switches of answering relay 164, alternate contact and engaged armature switch of controlling relay 165 and grounded battery 167, completing the circuit to ground. Supervisory lamp or signal 166 is displayed due to the current flowing through the described 90 circuit, said display indicating that the link connector is in use.

The other circuit may be traced as follows: from ground through resistance 168, lower winding of electro-magnet 169, supervisory lamp 170, normal contact and spring switch 171 of ringing relay 172 and right hand contact and engaged uppermost one of the two bottom armature switches of answering relay 164, completing the circuit to grounded battery 167 over the circuit already traced. Supervisory lamp 170 is not energized by the current flowing through this circuit, on account of the combined resistance of the lower winding of electro-magnet 169 and resistance 168. However, electro-magnet 169 is energized by said current and therefore its armature is attracted, the pawl attached thereto engaging ratchet wheel 173. Said pawl when so engaged has two functions; first, to prevent the return to normal position of ratchet wheel 173 when same is being rotated by its step-by-step motion; second, to close a circuit through electro-magnet 174 which furnishes the rotating means. This circuit may be traced as follows: from ground through electro-magnet 174, ratchet wheel 173, pawl and armature of electro-magnet 169, interrupter 175 and grounded battery 167, completing the circuit to ground. Interrupter 175 rotates at any desired speed and the exposed metallic portion thereof is such that electro-magnet 174 is allowed to advance ratchet wheel 173 one step for each impulse. Switch arm 176 is rotated by the step-by-step motion of ratchet wheel 173 and after the lapse of a fixed time interval engages contact segment 100 105 110 115 120 125

177 and thereafter successively engages contact segments 178 and 179, further rotation being impeded by stop 180. Upon engaging segment 179, the circuit through resistance 168 to ground is shunted by a low resistance path which allows supervisory lamp 170 to become energized. This shunt circuit may be traced as follows: from the right-hand terminal of said resistance 168 to winding of supervisory operator's relay 181 (which is of low resistance and operated by the current flowing in this circuit), switch arm 176 and engaged contact segment 179, completing the circuit to ground. However, during the time that has elapsed while switch arm 176 was rotating, a connection has been made by the operator to the called for line, and therefore ringing relay 172 was actuated, its top armature switch engaging spring switch 171, without disconnecting the same from its normal contact in the case of a "waiting" connection or disconnecting the same in the case of a connection to an idle line. In the first case, supervisory lamp 182 would have been energized as well as supervisory lamp 170; in the second case the former lamp would have been energized and the latter de-energized. In either case current would have continued to flow through electro-magnet 169, thereby causing the step-by-step motion of ratchet wheel 173 to continue.

The three supervisory lamps 170, 182 and 183 are preferably mounted as hereinbefore described in relation to the same lamps in Figure 1 and the signals displayed by them are the same. However, they are mounted at the switchboard position of a special supervisory operator; supervisory lamp 166 being the only one mounted at the connecting operator's position.

If supervisory lamps 170 and 182 were energized, the special supervisory operator would know that the calling party had been "waiting" for the called for party for a period represented by the elapsed time since ratchet wheel 173 began its rotation and switch arm 176 engaged contact segment 179. As the purpose of this supervisory system is not only to relieve the connecting operator of supervisory duties, but to free the link connectors from "active" connections as soon as possible, thereby obviating a possible shortage of link connectors at the connecting operator's position, the special supervisory operator on observing said signal would depress key 184, which corresponds to the same link connector as the supervisory lamps 170, 182 and 183, closing thereby a talking circuit which may be traced as follows: from the sub-station telephone apparatus through tip contact of answering plug 185, non-inductive resistance 186, engaged contact and lowermost armature switch of the two bottom ones of answering relay 164, uppermost spring

switch and engaged contact of key 184, lowermost one of the two top armature switches and engaged contact of supervisory operator's relay 181, supervisory operator's telephone receiver 187, secondary of supervisory operator's induction coil 188, condenser 189, contact and engaged bottom armature switch of said relay 181, contact and engaged center spring switch of key 184, top armature switch and engaged contact of answering relay 164 and ring contact of answering plug 185, completing the circuit through the sub-station telephone apparatus. Due to this circuit the special supervisory operator can converse with the "waiting" party at the calling sub-station and, if desired, inform said party that the called for line has not yet been released from its "busy" connection and that said supervisory operator will call said calling party when connection can be obtained. Having obtained the numbers of both calling and called sub-stations the calling party may be informed that he can replace his telephone receiver upon its switch-hook. Upon replacing said receiver upon its switch-hook, answering relay 164 and ringing relay 172 are de-energized, as hereinbefore described, and therefore the circuit is opened through supervisory lamps 170 and 182, which are therefore extinguished. The circuit through electro-magnet 169 being also opened, the same releases its armature pawl and spiral spring 190 returns ratchet wheel 173 and switch arm 176 to their normal positions.

If supervisory lamp 182 alone had been energized, the supervisory operator would have known that the called for sub-station's call bell had been rung for a period represented by the elapsed time necessary for the rotation of switch arm 176, and as the depression of key 184 opened the circuit for the ringing current delivered to the bottom armature switch of ringing relay 172, by disengaging the lowermost of the three spring switches of key 184 from its normal contact, said current, which returns to ground through winding 191 of the repeating coil, cannot interfere with the conversation between the calling sub-station and the special supervisory operator, therefore said operator is enabled to inform the calling party that the called sub-station does not answer. When the calling party replaces the receiver upon its switch-hook, ratchet wheel 173 is released, as has been described.

If the called sub-station responds, previous to said replacing of the receiver, then ratchet wheel 173 is released and switch arm 176 returned to its normal position by means of the de-energization of electro-magnet 169 due to the fact that current flows through its upper winding which is in opposition to the current flowing in its lower

winding. A circuit for this current may be traced as follows: from ground through resistance 168, said upper winding, supervisory lamp 183, right hand contact and engaged lowermost one of the two top armature switches of calling relay 192 (energized when the called sub-station responded), contact and engaged armature switch of controlling relay 165 and battery 167, completing the circuit to ground. It will therefore be seen that if the called sub-station responds, previous to the engagement of switch arm 176 with contact segment 179, no supervisory signal will be displayed at the special supervisory operator's position.

The described actuation of calling relay 192 closes another circuit through supervisory lamp or signal 166 which may be traced as follows: from ground through said lamp or signal, left hand contact and engaged lowermost one of the two top armature switches of calling relay 192, contact and engaged armature switch of controlling relay 165 and grounded battery 167, completing the circuit to ground.

Due to this circuit and the one already traced through supervisory lamp or signal 166, the same remains displayed as long as either or both of the calling and called sub-station telephone receivers remain off their respective switch-hooks.

Electro-magnet 169 remains de-energized as long as both connected sub-stations have their telephone receivers removed from their respective switch-hooks, as current flows through supervisory lamp 170 when the de-energization of ringing relay 172 re-engaged spring switch 171 with its normal contact. Supervisory lamps 170 and 183 are not energized, however, due to resistance 168, as hereinbefore mentioned.

When either the calling or called party replaces the sub-station receiver upon its switch-hook and the other party does not so do, then either answering relay 164 or calling relay 192, as the case may be, is de-energized and consequently the circuit opened through supervisory lamp 170 or 183, as the case may be, and therefore through one of the windings of electro-magnet 169. The current flowing through the remaining winding of said electro-magnet causes it to engage its armature pawl with ratchet wheel 173 and the latter begins its step-by-step motion. If the party who is still connected to the link connector does not replace the sub-station receiver upon its switch-hook before switch arm 176 engages contact segment 179, supervisory lamp 170 or 183, as the case may be, will be displayed and the special supervisory operator would connect her telephone set with the link connector, in the manner hereinbefore described. Should the connected sub-station be the called one, telephonic connection between

said sub-station and said operator is also established by the depression of key 184, due to the connection of the contacts of the two upper spring switches of said key to windings 193 and 194 of the repeating coil.

If said connected party is waiting for another connection to a sub-station, the special supervisory operator depresses key 195 which opens the connection to grounded battery 167 from both the calling and called tip contacts of answering plug 185 and calling plug 196. Therefore, whichever sub-station may be the connected one, the circuit is broken through the link connector and the corresponding line signal of the formerly connected line would be displayed at the connecting operator's position, the connecting operator treating the call as if it was a new one.

If the special supervisory operator obtains no response from the connected sub-station, the display of either supervisory lamp 170 or 183 would indicate whether it was the calling or called sub-station which had its receiver off its switch-hook, the number associated with said lamps at said supervisory operator's position would indicate the number of the link connector used and therefore the connecting operator's position, from whom could be obtained the number of the line to which the answering or calling plug, as the case may be, of said link connector was connected. The usual procedure when a sub-station telephone receiver is left off its switch-hook would be carried out and the link connector released by depressing key 195, causing the de-energization of supervisory lamp or signal 166 at the connecting operator's position.

The interposition of supervisory operator's relay 181 in the associated circuit is to prevent the connection of the supervisory operator's telephone set to the link connector until switch arm 176 has engaged contact segment 179, thereby preventing said operator from accidentally, or deliberately, interfering with a conversation passing through the link connector or listening thereto; and also preventing the release of the link connector by the accidental or deliberate depression of key 195, as a shunt circuit around the spring switch and normal contact of said key is closed by the top armature switch and normal contact of said relay 181. Therefore if key 195 is depressed before relay 181 has actuated, the circuit from the calling or called, or both sub-stations, is not opened thereby.

Should the connecting operator be confronted with a shortage of idle link connectors, key 197, which is located at the position of the connecting operator, is depressed, whereupon a circuit is closed which may be traced as follows: from ground through contact and engaged spring switch

of key 197, release relay 198, and resistances 199 corresponding to all the link connectors of said position whose associate switch arms 176 may be engaged with contact segments 177 or 178, said segments and switch arms, the associate supervisory operator's relays 181, the associate windings of electro-magnets 169, the associate supervisory lamps 170, 182 or 183, as the case may be, completing the circuit through grounded battery 167 by way of the engaged armature switches of the answering, ringing or calling relays.

Relay 198 actuates, due to the current flowing in this circuit (provided there are idle link connectors at said position) and the engagement of its armature switch with its contact establishes another connection to ground through said relay, which thereby remains actuated, after the release of key 197, as long as any switch arms 176 of the corresponding position are in engagement with contact segments 177 or 178.

It has been hereinbefore mentioned that supervisory lamps 170, 182 and 183 were not energized by the current passing through them and electro-magnet 169, when in series with resistance 168, due to the resistance of the latter. However, the circuit just traced shunts said resistance by resistance 199 in series with the winding of release relay 198, and as said shunt circuit reduces the resistance in series with said supervisory lamps the latter are now energized, provided, of course, that their battery connections have been closed by the actuation of answering, ringing or calling relays 164, 172 or 192. As switch arm 176, when it engages contact segment 177, closes said shunt circuit through all of resistance 199 and when it engages contact segment 178 closes said shunt circuit through a part only of said resistance, the supervisory lamps receive more or less current according to whichever of said contact segments is so engaged. Therefore their illuminating power will vary accordingly.

When switch arm 176 engages contact segment 179 there is no resistance in the circuit between said switch arm and ground. Therefore said supervisory lamps whenever displayed have low, medium or high illuminating power. Low representing the shortest connected period, medium the intermediate period and high the complete elapsed time period of the rotation of switch arm 176.

Therefore, when the connecting operator depressed key 197, thereby illuminating, as described, those supervisory lamps associated with link connectors not being used for conversational purposes, the special supervisory operator would first release, as hereinbefore described, those link connectors which had been but partly connected or disconnected for the longest time, as shown by the in-

sity of the illumination of said supervisory lamps.

Release relay 198 remains actuated until the last one of such link connectors is released, whereupon it becomes de-energized and its armature switch disengages its contact, opening the shunt circuit which cannot again be closed until key 197 is depressed again.

In Figure 8 I have illustrated a special cord circuit adapted to be used at the described supervisory operator's position.

When the supervisory operator receives a request to obtain a connection for a party who has been "waiting" for a busy line for the prescribed time interval, and has been released from the "waiting" connection, special plug 200 is inserted in the multiple jack (located at said supervisory operator's position) associated with the called for busy line. A circuit is thereby closed which may be traced as follows: from ground through the winding of the cut-off relay, sleeve of said multiple jack, waiting relay 201, spring switch 202 and normal contact of said relay, "waiting" interrupter 203 and grounded battery 204 completing the circuit to ground. Waiting relay 201 actuates similarly to the hereinbefore described ringing relay 40 (Figure 1), but none of its armature switches engage their respective contacts as long as there is another link connector in a "talking" or "ringing" condition associated with the same line. However, as soon as said line becomes idle, then waiting relay 201 receives sufficient current for its actuation and its respective armature switches and spring switches engage their contacts. When the uppermost one of the two bottom armature switches of said relay engages spring switch 202 it disengages the latter from its normal contact, thereby opening the circuit through "waiting" interrupter 203, but only after having first substituted a connection to "talking" interrupter 205.

The object in this arrangement is so that any further busy tests made on multiple jacks will give a "talking" busy test instead of the "waiting" busy test and will therefore allow a new "waiting" connection to be made to the line.

The engagement of spring switch 202 with its left hand alternate contact, short-circuits a part of the winding of waiting relay 201, the object being to assist in preventing a "ringing" or "talking" connection being made as was described in relation to ringing relay 40 (Figure 1). The engagement of said switch with its right hand alternate contact closes a circuit which may be traced as follows: from ground through the normal contact and uppermost one of the two bottom armature switches of special cut-off relay 206, special line lamp 207, resistance 208, said contact and spring switch 202, the en-

gaged armature switch, interrupter 205 and grounded battery 204, completing the circuit to ground. Special line lamp 207 is only partially illuminated due to resistance 208 preventing sufficient current from flowing to fully illuminate the same.

This partially illuminated special line lamp indicates to the special supervisory operator that the line is now idle, and therefore said operator rings the sub-station that was formerly "waiting" upon said line and if the party thereat still desires connection with said line, the supervisory operator connects said sub-station to special jack 209 by means 10 of one of the already described forms of link connectors or by other means. When the calling plug is inserted in special jack 209, current flowing from the sleeve contact of the same actuates special cut-off relay 206, 15 thereby extinguishing special line lamp 207. The circuit is closed to the called sub-station, from the tip and ring springs of special jack 209, by way of the top and lowermost one of the two bottom armature 20 switches of waiting relay 201 and their respective engaged contacts which are connected to the tip and ring contacts of special plug 200, which is inserted, as described, in the multiple jack of the called line.

20 When the called party replaces the sub-station receiver upon its switch-hock, the regular link connector is released in the manner fully described hereinbefore, therefore the current from the sleeve contact of the calling plug is cut-off and special cut-off relay 206 is de-energized and its armature switches re-engage their contacts. Line lamp 207 is again partially illuminated as the circuit closed through waiting relay 201 25 has not been broken. The special supervisory operator noting from the link connector supervisory signal or signals, or the partially illuminated line lamp that the connected parties have replaced their telephone receivers, removes the regular link connector from special jack 209 and special plug 200 from the multiple jack in which it is inserted.

Whenever special plug 200 is inserted in 30 one of the regular multiple jacks and the sub-station associated therewith should initiate a call, the same is at once signalled to the special supervisory operator by the full illumination of line lamp 207, who thereupon attends to the call through special jack 209, or, by removing special plug 200 from the multiple jack, restores the regular line relay and lamp of said line to the control of the calling sub-station, said line lamp thereupon signalling the regular connecting operator in the usual manner. The circuit by means of which said special line lamp is 35 fully illuminated may be traced as follows: from ground through the upper winding of special line relay 210, top armature switch

and normal contact of special cut-off relay 206, top armature switch and engaged contact of waiting relay 201, ring contact of special plug 200, ring spring of the connected multiple jack, sub-station apparatus of the 40 line initiating the call, tip spring of said multiple jack, tip contact of special plug 200, contact and engaged lowermost one of the two bottom armature switches of waiting relay 201, normal contact and lowermost 45 one of the two bottom armature switches of special cut-off relay 206, lower winding of special line relay 210 and grounded battery 204, completing the circuit to ground. Special line relay 210 is actuated by the current 50 flowing through the described circuit and the engagement of its armature switch with its contact short-circuits resistance 208, thereby allowing sufficient current to pass to fully illuminate special line lamp 207. 55

All the various supervisory signals so far described are displayed when the link connector is in use and de-energized when the same are idle. If a supervisory signal is desired when the link connector is not in 60 use, the form illustrated in Figure 9 may be used. In this figure only the connections involved with the supervisory signals are shown, as the relays and their other functions are the same as has been already amply described in relation to Figure 1.

When answering relay 211 (25 in Figure 1) and controlling relay 212 (23 in Figure 1) actuate, a circuit is closed which may be traced as follows: from ground through 65 answering supervisory lamp 213 (57 in Figure 1), normal contact and spring switch 214 of ringing relay 215 (40 in Figure 1), left hand alternate contact and engaged bottom armature switch of answering relay 211, normal contact and bottom armature switch of calling relay 216 (39 in Figure 1), alternate contact and engaged armature switch of controlling relay 212 and grounded battery 217, completing the circuit to ground. 110

Supervisory lamp 213 is energized by the current passing through this circuit. When a "waiting" connection is made, the top armature switch of ringing relay 215 engages 115 spring switch 214 without disengaging the same from its normal contact, therefore supervisory lamp 218 is also energized. When a "ringing" connection is made, the disengagement of said spring switch from its normal contact opens the circuit through supervisory lamp 213 and lamp 218 alone remains 120 energized. When the called party responds the actuation of calling relay 216 causes its bottom armature switch to engage its two alternate contacts, closing a circuit through the right hand one and calling supervisory lamp 219, which is energized thereby, and closing again through the left hand one and the right hand contact of the bottom armature switch of answering relay 211, the cir- 125

cuit opened through said armature switch when the bottom armature switch of calling relay 216 disengaged its normal contact. As ringing relay 215 was de-energized by the actuation of calling relay 216, lamp 218 is extinguished and lamps 213 and 219 remain illuminated.

When both calling and called parties replace their receivers upon their switch-hooks, de-energizing thereby answering relay 211 and calling relay 216, the bottom armature switches, disengaging their alternate contacts and engaging their normal contacts, open the circuits through answering and calling supervisory lamps 213 and 219 and close a circuit through "disconnect" supervisory lamp 220. This latter circuit may be traced as follows: from ground through said lamp, normal contact and bottom armature switch of answering relay 211, normal contact and bottom armature switch of calling relay 216, alternate contact and engaged armature switch of controlling relay 212, and grounded battery 217, completing the circuit to ground. It will be remembered that said controlling relay remains energized as long as the calling link connector is connected to a line. The operator seeing "disconnect" supervisory lamp 220 illuminated, takes down the connection, thereby de-energizing controlling relay 212 and extinguishing lamp 220.

As illustrated in Figure 9, lamp 220 is mounted with the other lamps under cap 221, which form of mounting may or may not be used as lamp 220 can be mounted separately. If mounted as shown and the other supervisory lamps are of various colors, as has been hereinbefore described, then "disconnect" supervisory lamp 220 would be of a different color; white, for example.

A much simpler form for a disconnect signal is shown in Figure 10, wherein but the one disconnect lamp is used. The circuit through "disconnect" supervisory lamp 222 is closed only when controlling relay 223 is energized, and both answering relay 224 and calling relay 225 have been de-energized. Other modifications may be made, taking advantage of a local circuit closed by the engagement of the armature switch of the controlling relay with its alternate contact.

In Figure 11 I have illustrated another method of obtaining the energization and de-energization of operator's relay 124 (Figures 5 and 6) and the prevention of its re-energization during an established telephonic connection between the two sub-stations. This method, as that illustrated in Figure 6, eliminates entirely the use of controlling relay 125 (Figure 5) and also allows the operator to connect two or more answering plugs to calling lines without having first inserted the corresponding calling plugs in the multiple jacks associated with the called

for lines. On account of operating conditions this is an advantage at times, as an operator may not be able to complete a call through to the called for line and may therefore answer another call from another sub-station.

If this had been done in the case of the various forms hereinbefore described, the calling parties would have been connected together through the operator's telephone set, as the latter is not removed from association with the answering plug until the calling plug is inserted in a jack.

This form also illustrates an original method of obtaining a delayed de-energization of the operator's relay when the calling plug is inserted in a jack so as to allow the operator to hear the first ringing signal, or to impress the first ringing signal on the line, as illustrated in Figure 5, when periodic ringing of long silent intervals is used. In said Figure 11 I have not illustrated anything but said alternative method of control of the operator's relay and the means whereby the operator's telephone set can be associated with but one link connector at a time, it being understood that the other functions, contacts, etc., are the same as shown in the preceding figures. In this figure I have shown said parts which pertain to two link connectors, indicating the latter by the letters A and B. A is intended to represent the first link connector at an operator's position and B the last link connector at said position.

The equipment and arrangement of all the link connectors between these two is identical to that of A and B and is represented in the figure by the dotted lines in the center of the drawing. When answering plug 226 of link connector A is inserted in the answering jack of the calling line and connecting key 227 is depressed, current flows from ground through the sleeve contact of said plug, the illustrated winding of relay 228 (which may be either the answering supervisory or answering relay as illustrated in the preceding figures), normal contact and top armature switch of calling relay 229, winding of operator's relay 230, engaged top and bottom spring switches of connecting key 227 and grounded battery 231, completing the circuit to ground. Relays 228 and 230 are actuated by the current flowing in this circuit and the engagement with its contact of the uppermost one of the two bottom armature switches of operator's relay 230 closes another circuit through the winding of the same when connecting key 227 is released, which can be done as soon as operator's relay 230 has actuated. This circuit may be traced as follows: from ground through grounded battery 231, bottom spring-switch and normal contact of connecting key 227 of link connector A, bottom spring-switches and normal contacts of all

link connectors between A and B, top armature switch of operator's relay 230, engaged top and bottom spring switches of connecting key 227 and grounded battery 231, completing the circuit to ground. This circuit may be traced as follows: from ground through grounded battery 231, bottom spring-switch and normal contact of connecting key 227 of link connector A, bottom spring-switches and normal contacts of all link connectors between A and B, top armature switch of operator's relay 230, engaged top and bottom spring switches of connecting key 227 and grounded battery 231, completing the circuit to ground.

the connecting keys of the other link connectors at the same switchboard position, right hand windings of release relays 232 and 233, the multiplied armature switches 5 and contacts of said relays and contact and engaged uppermost one of the two bottom armature switches of operator's relay 230, completing the circuit to ground as already traced through the winding of said relay. 10 Due to the current flowing through this circuit operator's relay 230 remains actuated as long as this circuit is not opened at the multiplied armature switches of release relays 232 and 233. The right hand windings of release 15 relays 232 and 233 are such, or the armature switches are so regulated, that not enough current can flow through said windings to cause the actuation of said relays. However, said windings constitute locking windings 20 and the current flowing through them maintains the respective armature switch of one or the other of the relays disengaged from its contact when the disengagement has once taken place, due to the current flowing 25 through the corresponding left-hand winding. When calling plug 234 is inserted in a jack, a circuit is closed, first through the left hand winding of one of said release relays, and then, after an interval, through the left hand winding of the other release relay. This circuit may be traced as follows: from 30 ground through the sleeve contact of calling plug 234, contact and engaged lowermost one of the two bottom armature switches of 35 operator's relay 230, left hand winding of either release relay 232 or 233 (according to the position of interrupter 235), interrupter 235 and grounded battery 231, completing the circuit to ground. The current thus allowed to flow through the left hand windings of release relays 232 or 233, whenever 40 interrupter 235 engages one or the other of its brushes, is sufficient to cause the actuation of the corresponding relay, the current flowing through the corresponding right hand winding maintaining the same in its actuated condition when interrupter 235 disengages its corresponding brush. 45

Interrupter 235 is so arranged that its exposed metallic portion alternately engages its respective brushes at a fixed time interval, therefore release relays 232 and 233 are energized one after the other, the time interval between the energization of one and the other having, as its minimum, the period of rotation of said interrupter from the disengagement of its metallic portion with one brush to its re-engagement therewith on its next revolution, and as its maximum, the period of rotation from the engagement of its metallic portion with one brush and the opposite one. If the latter period is one second, then the former would be a little less than two seconds, according to the length of the exposed metallic portion of said inter-

rupter. As the circuit through the winding of operator's relay 230 is not opened until both the armature switches of release relays 232 and 233 have disengaged their contacts; by the means described I obtain a delayed de-energization of said operator's relay when the calling plug is inserted in a jack and therefore a delayed opening or closing of the circuits controlled by said operator's relay. 70

Whichever of the two release relays is first actuated the current flowing through its right hand winding maintains it so actuated, but when the second relay is energized the circuit through both the right hand windings is opened and in consequence the armature switches of both relays re-engage their respective contacts, but not before operator's relay 230 has become de-energized and disengaged its two bottom armature switches from their respective contacts, thereby opening the circuit through said relay (which cannot again be closed until connecting key 227 is once more depressed) and the circuits through the right and left hand windings of release relays 232 and 233 (which cannot again be closed until another link connector at the same position is used in the same manner as has been described). To insure the disengagement from their contacts of the armature switches of operator's relay 230, a central winding may or may not be used on release relays 232 and 233 as shown by the dotted lines. This winding is of a high resistance and is short circuited until both the armature switches of said relays have disengaged their contacts, whereupon said short circuit is removed and current continues to pass through the right hand windings of said relays and said central winding now in series therewith as long as the uppermost one of the two bottom armature switches of operator's relay 230 remains engaged with its contact. On account of the high resistance of this central winding of release relays 232 and 233, while the same receive enough current to maintain their actuation, operator's relay 230 does not receive sufficient to maintain its actuation, therefore it becomes de-energized. 95

It will be seen that the time which must elapse before said release takes place is a constant factor, which cannot vary from the proscribed limits furnished by the rotation of interrupter 235. On account of its simplicity and reliability, and freedom from sensitive adjustments, etc., I prefer this method of obtaining a delayed de-energization of the operator's relay rather than the one described in reference to Figure 5. It will readily be seen that release relays 232 and 233, as illustrated in Figure 11, could be substituted for slow acting relay 145 shown in Figure 5 and still retain controlling relay 125 associated with the link connector instead of using a manually operated 100 105 110 115 120 125 130

key to initially energize the operator's relay, as is illustrated by connecting key 227 in Figure 11.

While this central winding of the release 5 relays is not essential, as in practice operator's relay 230 is made so that its armature switches release their contacts with great rapidity when the circuit through its winding is opened, it may well be used, if desired, to overcome any tendency to slow action 10 on the part of said operator's relay.

The delayed de-energization of operator's relay 230, does not prohibit the operator from answering another calling line, immediately 15 after having inserted a calling plug in a jack, as before another answering plug could be inserted in the answering jack associated with said line and connecting key 227 (corresponding to the link connector used) depressed, both of the release relays 232 and 233 would have been energized and therefore the operator's relay of the first used link connector would have been de-energized and the operator's telephone set disassociated 20 from the same.

When the called for sub-station responds, the actuation of calling relay 236 and the disengagement of its top armature switch from its contact opens the connection from 25 the sleeve of answering plug 226 to the winding of operator's relay 230, therefore an operator can neither accidentally nor deliberately connect her telephone set to a link connector which is being conversed upon or held 30 for conversation.

If the operator finds it impossible to complete a call for a calling party and pending the opportunity to complete the same needs to answer a call from another sub-station, 40 the telephone set of said operator is disconnected from link connector A associated with the first mentioned sub-station when connecting key 227, associated with link connector B, used for the second call, is depressed. 45 When said key is depressed the disengagement of its bottom spring switch from its contact opens the circuit through the right hand windings of release relays 232 and 233 and therefore through the winding of operator's relay 230 of link connector A by way of 50 the contact and engaged uppermost one of the two bottom armature switches of said relay, the effect being the same as if release relays 232 and 233 had opened the circuit by disengaging their respective armature switches from their contacts.

The consequent de-energization of operator's relay 230 of link connector A, removes 60 the operator's telephone set from association with said link connector. Operator's relay 230 of link connector B is energized and said set therefore associated with said link connector by the current which flows by way of the engaged top and bottom spring

switches of connecting key 227 direct to 65 grounded battery 231 by way of the normal contacts and bottom spring switches of all the connecting keys 227 pertaining to the link connectors between A and B.

When connecting key 227 of link connector B is released, its bottom spring switch re-engages its contact before it becomes disengaged from the top spring switch, therefore the circuit through the right hand windings of release relays 232 and 233 is 70 closed again and current flows by way of the contact and engaged uppermost one of the two bottom armature switches of operator's relay 230 of link connector B, and the winding of said relay, therefore said relay remains actuated. As more than one connecting key 227 is not depressed at one time, it will be seen that the operator's telephone set will always be associated with the link connector whose corresponding connecting key 227 has last been depressed. When the call for link connector A can be completed through, connecting key 227 of the same is again depressed and calling plug 234 75 inserted in the multiple jack of the called for line. It will be readily understood that the same action as the described one would take place when any of the link connectors between A and B are used in place of the latter.

I have illustrated in Figure 12 another means by which the disconnection of the operator's telephone set is obtained from a link connector whose answering plug is connected to a calling line but whose calling plug cannot be connected through to the called sub-station. This means is adaptable to the link connectors illustrated in Figures 1, 4 and 5, wherein said disconnection of the operator's telephone set is obtained by the energization of controlling relays 23, 100 105 106 and 125 (of Figures 1, 4 and 5, respectively) which normally takes place when a ground connection is made to the sleeve of the calling plug when the same is inserted in a jack. If for any operating reason the call cannot be connected through at the time and the operator needs to answer another call before completing the first call, then the calling plug of the link connector used for said first call is temporarily inserted in an operator's set disconnector such as 236 (Figure 12) which is connected to ground through resistance 237. Disconnector or spring clip 236 is so arranged that it 110 115 120 125 engages only the sleeve contact of the inserted plug, so that when the ringing relay of the associated link connector is actuated, due to the current allowed to flow through the same from the grounded spring clip, there is no circuit for the ringing current from the tip and ring contacts of said calling plug. As the actuation of said ringing re-

lay causes the actuation of the controlling relay and the actuation of the latter causes the de-energization of the operator's relay which disconnects the operator's telephone set from the associated link connector, (as has been hereinbefore amply described) as long as the calling plug remains engaged with spring clip 236, the operator is free to connect another answering plug to a calling line. When the call for the first line can be completed through, the calling plug is removed from spring clip 236 and inserted in the multiple jack in the usual manner. Resistance 237 is used only on account 15 of economy in current consumption. It can be dispensed with if desired.

While I have shown but one form of spring clip 236, it will readily be seen that any means which connects the sleeve contact of the calling plug to ground would serve the same purpose. As illustrated, spring clip 236 furnishes a simple means to which it is easy to connect more than one plug if necessary. Such a clip or substitute 25 therefor may be mounted on any convenient part of the switchboard at every operator's position.

Another modification, without departing radically from the principles involved, is 30 the adaptation of the described telephone system to trunking telephone calls between telephone exchanges.

The simplicity of operation of the described ringing system, which does not rely 35 on the marginal action of a relay, or similar methods, for its disconnection from the called for line, and the comparative freedom from delicacy of operation of the calling supervisory relay, which can have a winding 40 of high inductance, owing to the fact that the non-inductive resistance (which allows the voice currents to pass said relay) is bridged across the inductive winding only after said relay has attracted its armature and therefore needs but a small magnetic 45 flux to maintain said armature attracted, all allow a trunking system to be used which would be impossible with other systems.

In Figure 13 I have illustrated a trunk 50 line adapted to be used with the already described forms of my telephone system. This trunk line is of the utmost simplicity, as the controlling factors for its operation are all contained in the apparatus associated 55 with the already described link connectors. In other words, said trunk line is virtually a mere extension of the calling link connector.

As in practice the switchboard that handles the calls from the calling sub-stations 60 is generally referred to as the "A" board and the operator who handles the calls thereat referred to as the "A" operator; while the board where the outgoing trunks terminate at the other exchange is referred to as the

"B" board and the operator thereat as the "B" operator, I have kept to the same nomenclature.

The trunk lines originate in spring jacks at the "A" switchboard, which may or may not be multiplied thereat, and terminate directly in link connectors at the "B" switchboard, there being only calling plugs used. The means by which the "A" operator indicates to the "B" operator the number to which the trunk is to be connected is not described herein, as it forms no part of the present invention.

Referring to Figure 13, the tip and ring springs of spring jack 238, at the "A" board, connect directly with the left hand winding 80 of trunk relay 239 at the "B" board. This winding is of such a high resistance that the direct current which is impressed upon the line, at intervals between alternations of the ringing current, by way of the contacts of the ringing relay of a link connector at the "A" board, while sufficient to maintain relay 239 actuated, is not sufficient to cause the actuation of the calling supervisory relay of said link connector at the "A" board. 85 When a calling plug is inserted in the trunk jack, resistance 240 takes the place of the usual cut-off relay, in order to obtain the actuation of the ringing and calling relays, etc. Therefore ringing current is at once impressed on the trunk line and trunk relay 239 is actuated by the current flowing 90 through its left hand winding, the actuation of said relay being brought about by both the alternating and intermittent direct current so impressed upon the trunk line. The actuation of said relay, when the trunk plug is inserted in a multiple jack of the called for line, closes a circuit which may be traced 95 as follows: from ground through the cut-off relay and sleeve of the multiple jack, sleeve of calling plug 241, trunk supervisory lamp or signal 242, engaged contact and armature switch of trunk relay 239 and 100 grounded battery 243, completing the circuit to ground. The cut-off relay is actuated by the current flowing in this circuit and trunk supervisory lamp or signal 242 is displayed. The call bell or annunciator at 105 the called for sub-station is operated by the ringing current from the "A" board, a circuit for which may be traced as follows: from the tip spring of trunk jack 238, through tip contact of calling plug 241, tip spring of the multiple jack to which connection has been made, sub-station call bell or 110 annunciator, (as described in relation to sub-station 1 of Figure 1) ring spring of said multiple jack, right hand winding of trunk relay 239 (which is of low resistance) and non-inductive resistance 244, to the ring 115 spring of trunk jack 238. (The circuit from the tip and ring springs of trunk jack 238

120

125

through the link connector at the "A" board is the same as has been fully described in relation to the preceding figures.)

When the party at the called sub-station 5 responds, the high resistance left hand winding of trunk relay 239 is shunted by the low resistance path closed at the called sub-station when the receiver thereat is removed from its switch-hook; therefore the calling 10 supervisory relay and the calling relay at the "A" board are energized and the ringing relay de-energized. The direct current flowing through the right hand winding of trunk relay 239 maintains the actuation of the 15 same, notwithstanding the described shunting of the left hand winding of the same. The two sub-stations can now converse with each other as non-inductive resistance 244 allows the voice currents to pass across the 20 right hand winding of trunk relay 239 and the high resistance and impedance of the left hand winding of the same does not impede the voice currents from reaching the repeating coil associated with the link connector at the "A" board. Battery current 25 for operating the transmitter at the called sub-station is also transmitted from said repeating coil.

When the called party replaces the receiver upon its switch-hook, the low resistance shunt around the left hand winding of trunk relay 239 is removed and as said winding does not allow enough current to pass to maintain the actuation of the calling supervisory relay at the "A" board, said relay 30 is de-energized opening the connection to the trunk line by the de-energization of the calling relay. Trunk relay 239 is thereupon de-energized and its armature switch disengaging its normal contact, extinguishing trunk supervisory lamp or signal 242 and de-energizing the cut-off relay, thereby automatically restores the called line to its normal idle condition.

It will be seen that party line ringing 45 can be controlled by the "A" operator, who can impress any of the various classes of ringing current upon the trunk line.

The busy tests for the described trunk line 50 and for that shown in Figure 15 are not made with the tip of the trunk plug, as is usually the case, but are made by use of the apparatus illustrated in Figure 14 wherein 245 represents a metallic thimble of any convenient form adapted to be worn on the end of one of the fingers of one or both hands of the "B" operator. Previous to inserting trunk plug 241 (Figure 13) into a multiple jack, the sleeve of said jack is 55 touched by thimble 245 and if the same is at a potential above that of the earth (as is the case when a busy line is tested) the current flowing to ground through primary 246 which is connected to thimble 245, induces a 60 current in secondary 247 which is connected

to the "B" operator's telephone receiver. Secondary 247 is of a preferably high resistance so as not to impede the voice currents from the "A" operator's set which pass from lines 248 and 249 to said "B" operator's receiver.

The use of the trunk circuit illustrated in Figure 13 is limited to locations where the furthest connected sub-station from the "B" board would not be too far from the "A" 75 board to receive therefrom sufficient current to operate the sub-station transmitter.

Where such a condition does not apply, the circuit illustrated in Figure 15 may be used; wherein the winding of trunk relay 250 corresponds to the left hand winding of trunk relay 239 (Figure 13), and the winding of trunk supervisory relay 251 corresponds to the right hand winding of said relay 239. Therefore when ringing current 80 is impressed upon the trunk line the consequent actuation of trunk relay 250 closes a circuit which may be traced as follows: From grounded battery 252 through the armature switch and alternate contact of 85 trunk relay 250, trunk ringing supervisory lamp or signal 253 and sleeve contact of trunk plug 254, completing the circuit to ground through the cut-off relay when said plug is inserted in a multiple jack. The 90 cut-off relay and trunk ringing supervisory lamp or signal 253 are both energized by the current flowing in this circuit.

Ringing current, which will be of a class 95 according to whether a party line key has 100 been depressed or manipulated at the "A" board or not, is impressed upon the called line through a circuit which may be traced as follows: from the tip spring of trunk jack 255, spring switches 256 and 257 of connecting relay 258, winding of trunk supervisory relay 251, tip contact of trunk plug 254, tip spring of the multiple jack in which said plug is inserted, the sub-station 105 call bell or annunciator, ring spring of said multiple jack, spring switch 259 and normal contact of connecting relay 258, and ring spring of trunk jack 255, completing the circuit through the "A" board ringing 110 devices, as has been hereinbefore described. Trunk supervisory relay 251 is actuated by the current flowing in this circuit.

When the called sub-station responds, the high resistance winding of trunk relay 250 is shunted by the low resistance path formed at the called sub-station and its armature switch disengages its alternate contact and reengages its normal contact, thereby extinguishing trunk ringing supervisory lamp 120 253. The closing of the low resistance circuit at the called sub-station causes the actuation of the calling relay and the de-energization of the ringing relay at the "A" board and therefore constant direct current 125 from the repeating coil of the link connector 130

thereat now flows through the trunk circuit. As trunk supervisory relay 251 is in series relation with the sub-station circuit, it remains actuated and when the armature switch of trunk relay 250 re-engages its normal contact, the circuit through the sleeve contact of trunk plug 254 which was opened by the disengagement of said armature switch from its alternate contact is closed again but this time through the winding of connecting relay 258 instead of lamp 253. This circuit may be traced as follows: from ground through the cut-off relay, sleeve of the multiple jack, sleeve contact of trunk plug 254, winding of connecting relay 258, armature switch and engaged alternate contact of trunk supervisory relay 251, normal contact and armature switch of trunk relay 250 and grounded battery 252, completing the circuit to ground. Due to the current flowing in this circuit both the cut-off relay and connecting relay 258 are actuated. The engagement of the top armature switch of said relay with spring switch 259 establishes a ground connection through winding 260 of the repeating coil to the ring contact of the trunk plug, previous to disengaging said spring switch from its normal contact and thereby breaking the connection from said ring contact to ground through the ring spring of trunk jack 255 and the repeating coil associated with the link connector at the "A" board. The engagement of the bottom armature switch of said relay with spring switch 257 establishes a connection from the live pole of grounded battery 252 through winding 261 of the repeating coil to the tip contact of the trunk plug, previous to disengaging said spring switch from spring switch 256 and thereby breaking the connection from said tip contact to the live pole of the grounded battery, through the tip spring of trunk jack 255 and the repeating coil associated with the link connector at the "A" board.

In this manner trunk supervisory relay 251 is maintained actuated, though the source of energizing current has been changed from the repeating coil at the "A" board to the repeating coil associated with the trunk circuit. As the top and bottom armature switches of connecting relay 258 connect current of the same polarity to the tip and ring contacts of trunk plug 254 as that connected thereto through the tip and ring springs of trunk jack 255, it is immaterial whether said armature switches engage their respective spring switches simultaneously or not.

When the bottom armature switch of connecting relay 258 disengages spring switch 257 from spring switch 256 it engages the former with its alternate contact and thereby bridges non-inductive resistance 262 across the inductive winding of trunk supervisory relay 251, allowing voice currents to pass

said relay. At the same time spring switch 256 has been allowed to engage its alternate contact thereby closing a circuit which may be traced as follows: from the tip spring of trunk jack 255, through said spring switch 256 and engaged alternate contact, windings 263 and 264 of the repeating coil, ring spring of trunk jack 255 and the hereinbefore described talking circuit of the calling link connector at the "A" board, completing the circuit back to said tip spring. The high resistance winding of trunk relay 250 is therefore shunted by the lower resistance and lower impedance path furnished by windings 263 and 264 of the repeating coil and therefore the voice currents from the repeating coil at the "A" board pass through said windings 263 and 264. Said trunk relay 250 is not actuated by the battery current from said repeating coil due to the low resistance shunt formed by said windings 263 and 264. As the called sub-station is now directly connected to windings 260 and 261 of the repeating coil, conversation can be carried on between the connected sub-stations.

The engagement of the uppermost one of the two bottom armature switches of connecting relay 258 with its right hand contact closes a circuit from grounded battery 252 through talking supervisory lamp or signal 265 which is thereby energized and its engagement with its left-hand contact short-circuits the upper half of the winding of connecting relay 258, the purpose of said short-circuit being the same as that hereinbefore described in relation to ring relay 40 in Figure 1, namely, to furnish means for preventing an accidental or deliberate connection to a busy line.

This short-circuit also furnishes current from grounded battery 252 to the lower half of the winding of connecting relay 258 independent of the armature switch of trunk supervisory relay 251, so that a momentary disengagement of said armature switch does not de-energize said connecting relay.

When the telephone receiver of the called substation is replaced upon its switch-hook, the circuit through trunk supervisory relay 251 is opened and therefore its armature switch re-engages its normal contact which is connected to the sleeve contact of trunk plug 254, therefore the current from grounded battery 252 flowing through the uppermost one of the two bottom armature switches and its engaged left hand contact of connecting relay 258 now has two paths offered to it, from the central terminal of the winding of said relay towards both ends of the same and as these windings are in opposition to each other, said connecting relay is consequently de-energized, opening said battery connection, de-energizing talking supervisory lamp or signal 265 and re-

storing the other connections controlled by said relay to their normal condition. The circuit through the sleeve contact of trunk plug 254 being opened by said de-energization, the cut-off relay associated with the called line is de-energized and the control of the line relay and line lamp or signal of the called line restored to the control of the called sub-station. The disengagement of spring switch 256 of connecting relay 258 from its alternate contact when said relay was de-energized, opened the circuit through windings 263 and 264 of the repeating coil, therefore the low resistance shunt

5 around the high resistance winding of trunk relay 250 is removed and as the current which can flow through said winding is not sufficient to maintain actuated the calling supervisory relay associated with the link

10 connector at the "A" board, which is connected to trunk jack 255, said calling supervisory relay is de-energized and said link connector circuits opened, as has been hereinbefore described.

15

If the telephone receiver had been replaced upon its switch-hook at the calling sub-station, previous to the response of the called sub-station, the consequent de-energization of the ringing relay of the link connector engaged with trunk jack 255 would have opened the circuit through the tip and ring springs of said jack, de-energized both trunk relay 250 and trunk supervisory relay 251 and consequently opened the circuit

20 through trunk ringing supervisory lamp or signal 253 and the sleeve contact of trunk plug 254. Therefore the cut-off relay would have been de-energized, the line relay and line signal restored to the control of the connected sub-station, said line would test idle at any multiple jack and the sub-station could initiate calls.

The calling link connector at the "A" board, the trunk circuit and the called line are all released for further connections by the replacing of the telephone receiver at the called sub-station on its switch-hook. Connections can be made from the released called sub-station regardless of the connection to a multiple jack associated with said line of the trunk plug of the released trunk circuit and the line will test idle at any multiple jack, as the only connection from the tip and ring limbs of said line, through said released trunk circuit, is through the winding of trunk supervisory relay 251 in series with the high resistance winding of trunk relay 250. As this latter winding is of not only high resistance but high impedance as well, the line lamp of the connected line is not energized thereby, nor are voice currents from the line allowed to pass through said winding. The same thing is true of the form shown in Figure 13, both of said forms being preferably intended for use where the

outgoing trunk calls are handled by a single operator, as were either of the forms illustrated in Figures 13 and 15 used where more than one operator handled the outgoing calls, ringing current might be impressed upon a line with which a released trunk circuit was connected and said current passing through the tip and ring contacts of the released trunk circuit would actuate relay 239 in Figure 13 and relays 250 and 251 in Figure 15. Therefore, when more than one operator handles the outgoing calls at the "B" board, I would prefer to use the embodiment of the system illustrated in Figure 16.

In this figure trunk relay 266 corresponds to trunk relay 250 in Figure 15, and it actuates as has been described in relation to said figure, excepting that the upper terminal of the winding of trunk relay 250 (Figure 15) was connected to ground through the ring spring of trunk jack 255 and the repeating coil of the link connector at the "A" board, while the upper terminal of trunk relay 266 (Figure 16) is connected direct to ground at the "B" board. If the "waiting" connections are used and this ground connection was made through the repeating coil at the "A" board then the calling party would receive a false "ringing" audible signal in the sub-station telephone receiver, due to the ringing current flowing through trunk relay 266 to maintain its actuation while the trunk link connector is in the "waiting" condition.

On receiving a call from the "A" operator, the "B" operator tests the called for line by engaging the tip of trunk plug 268 with the sleeve of a jack associated with said line and if the line tests idle inserts the plug into said jack. (The busy tests are described herein-after.) The engagement of the armature switch of trunk relay 266 with its alternate contact allows current from grounded battery 269 to flow through trunk ringing supervisory lamp or signal 270, which energizes the same. The insertion of said plug in the jack closed a circuit which may be traced as follows: from ground through the cut-off relay and sleeve of the engaged jack, sleeve contact of calling plug 268, resistance 271, top armature switch and normal contact of trunk controlling relay 272, winding of trunk ringing relay 273, spring switch 274 and normal contact of said relay, "waiting" interrupter 275 and grounded battery 269, completing the circuit to ground. The cut-off relay and trunk ringing relay 273 are both energized by the current flowing through this circuit, and a circuit is closed for the ringing current from the tip and ring springs of trunk jack 267, which may be traced as follows: from said ring spring through the contact and engaged middle one of the three top armature switches of trunk ringing relay 273, ring contact of trunk plug

268, sub-station call bell or annunciation, tip contact of said plug, right hand winding of trunk supervisory relay 276, lowermost one of the two bottom armature switches of 5 trunk ringing relay 273 and its engaged contact, and the tip spring of trunk jack 267, completing the circuit to the ring spring through the ringing devices associated with the link connector engaged with trunk jack 10 267 at the "A" board.

The engagement with its contact of the lowermost one of the three top armature switches of trunk ringing relay 273 closes a shunt circuit around resistance 271 which 15 may be traced as follows: from the right hand terminal of said resistance, lowermost one and normal contact of the two top armature switches of trunk calling relay 277, said armature switch and contact of trunk ringing relay 273, upper winding of trunk controlling relay 272, normal contact and top armature switch of said relay, completing the shunt circuit to the left hand terminal of resistance 271. The current flowing 20 through said shunt circuit is sufficient to cause the actuation of trunk controlling relay 272 and when its top armature switch disengages its normal contact, the circuit is opened through resistance 271 and all the 25 current flowing through the sleeve contact of trunk plug 268 and winding of trunk ringing relay 273 now flows through the upper winding of controlling relay 272.

The engagement of the uppermost one of 30 the two bottom armature switches of trunk ringing relay 273 with spring switch 274, connects the lower terminal of the winding of said relay direct to grounded battery 269 before the disengagement of said spring 35 switch from its normal contact disconnected said terminal from said battery by way of "waiting" interrupter 275. The engagement of said spring switch with its alternate contact short-circuits a part of the winding 40 of said relay, the purpose of which has been hereinbefore described.

When the called sub-station responds, 45 trunk relay 266 is shunted by a low resistance path, as has been hereinbefore described, and therefore its armature switch disengages its alternate contact, extinguishing thereby trunk ringing supervisory signal 270, and engages its normal contact thereby closing a circuit which may be traced as follows: from ground through the cut-off relay and sleeve contact of trunk plug 268, winding of trunk calling relay 277, left hand winding of trunk supervisory relay 276, uppermost one and engaged contact of the 50 three top armature switches of trunk ringing relay 273, normal contact and armature switch of trunk relay 266 and grounded battery 269, completing the circuit to ground. Trunk calling relay 277 is energized by the 55 current flowing through this circuit and its

uppermost and middle armature switches of the three top ones and its two bottom armature switches engage their contacts before the lowermost of the three top ones disengages its contact. The engagement of the middle 70 one of the three top armature switches with its contact connects the ring contact of trunk plug 268 to ground through winding 278 of the repeating coil and the engagement of the lowermost one of the two bottom armature switches with its two contacts bridges non-inductive resistance 279 across the right hand winding of trunk supervisory relay 276 and connects both to the live pole of grounded battery 269 through winding 280 of the repeating coil. The engagement with its contact of the uppermost one of the three top armature switches of calling relay 277 closed the circuit from the tip and ring springs of trunk jack 267 through windings 281 and 282 of the repeating coil. Therefore the two sub-stations are telephonically connected and conversation can take place between them as soon as trunk ringing relay 273 is deenergized, which takes place when the lowermost one of the three top armature switches of calling relay 277 disengages its contact, thereby opening the circuit through the winding of trunk ringing relay 273. The engagement with its left hand contact of the uppermost one of the two bottom armature switches of calling relay 277 closed a circuit through talking supervisory lamp or signal 283 and grounded battery 269, the energization of said lamp or signal being the 100 operator's assurance that the called sub-station has responded. The engagement of said armature switch with its right hand contact had established a connection to the live pole of grounded battery 269 from the lower terminal of the winding of trunk calling relay 277, previous to the breaking of the other connection to the same through the left hand winding of trunk supervisory relay 276 when the uppermost one of the three top armature switches of trunk ringing relay 273 disengaged its contact, therefore trunk calling relay 277 remains actuated.

When the telephone receiver at the called sub-station is replaced upon its switch-hook, trunk supervisory relay 276 is de-energized and the engagement of its armature switch with its normal contact short-circuits the winding of calling relay 277 which is thereby de-energized, opening the circuit through the sleeve contact of trunk plug 268, de-energizing the cut-off relay and thereby restoring the line relay and line signal to the control of the called sub-station. Therefore the line will test idle at any multiple jack associated with said line. At the same time the disengagement from its contact of the uppermost one of the three top armature switches of trunk calling relay 277, opens the circuit from the tip and ring springs of trunk plug 115 120 125 130

- 267 through windings 281 and 282 of the repeating coil, thereby removing the low resistance shunt from around the winding of trunk relay 266 and causing the calling 5 supervisory relay associated with the link connector engaged with trunk jack 267 at the "A" board to be de-energized and said link connector circuits opened, as has been hereinbefore described.
- 10 When the busy test was made on the sleeve of a jack of the called for line if the same had been busy said sleeve would have been at a potential above that of the earth and current would have flowed through the tip 15 contact of trunk plug 268, non-inductive resistance 279, bottom armature switch and normal contact of trunk controlling relay 272 and special primary 284 of the operator's induction coil to ground. This would 20 have caused a signal to be heard in telephone receiver 285 on account of its connection to secondary 286 of the induction coil. Secondary 286 is of a sufficiently high resistance and impedance as not to shunt the voice currents from lines 287 and 288, to any appreciable extent. When the busy test was made, if another link connector had been engaged with a jack multipled on the tested line and the same had been in the "waiting" condition, the signal produced in telephone receiver 285 would have been distinctive to "waiting" interrupter 275, as has been hereinbefore described in relation to Figure 1. If said link connector had been in a "ringing" or "talking" condition, the signal in said receiver would have been in the nature of a click, as constant current from grounded battery 269 would flow through primary 284 of the operator's induction coil. If the special "ringing" and "talking" busy tests described in relation to Figure 1 are desired, then the uppermost one of the two bottom armature switches of trunk ringing relay 273 would have been connected to grounded battery 269 through "ringing" interrupter 45 (Figure 1) and the corresponding armature switch of trunk calling relay 277 and the armature switch of trunk relay 266 would have been connected to "talking" interrupter 24 (Figure 1).
- 50 I have purposely shown Figure 16 without the two latter interrupters as they may or may not be used as desired, the only interrupter which is essential being "waiting" interrupter 275, (Figure 16) as the operator must be warned by the described busy signal if a "waiting" link connector is already connected to a tested line.
- When a connection is made to a busy line, 60 trunk ringing relay 273 is prevented from fully actuating in the same manner as has been hereinbefore described in relation to ringing relay 40 (Figure 1).
- However, the uppermost and lowermost 65 ones of its three top armature switches engage their respective contacts, though all the other armature switches do not engage their respective contacts, therefore trunk controlling relay 272 is energized by the current flowing through its upper winding and the disengagement of its armature switch from its contact prevents trunk ringing relay 273 from being energized again should the telephone receiver at the calling sub-station be replaced upon its switch-hook previous to the response of the called sub-station.
- Trunk controlling relay 272 has a lower locking winding which maintains said relay actuated as long as trunk plug 268 is inserted in a jack, its function and mode of operation 80 being the same as that described in relation to controlling relay 23 (Figure 1) and controlling relay 106 (Figure 4).
- In the event that the calling party replaces the receiver upon its switch-hook previous to the response of the called party, the consequent engagement of the armature switch of trunk relay 266 with its alternate contact would close the already described circuit through the engaged contact and uppermost one of the three top armature switches of trunk ringing relay 273 and the left hand winding of trunk supervisory relay 276 and when trunk calling relay 277 was consequently energized, the disengagement of the lowermost one of the three top armature switches from its contact would de-energize trunk ringing relay 273, thereby deenergizing the left hand winding of trunk supervisory relay 276 and as the right hand winding of said relay would not be energized (due to the fact that there is no closed circuit for direct current at the called sub-station which has not responded) its armature switch would engage its normal contact thereby short-circuiting the winding of trunk calling relay 277 and de-energizing the same. The same procedure would take place if the telephone receiver at the calling sub-station was replaced on its switch-hook when ringing current was being impressed upon the line. In both cases the called for line is automatically restored to its normal idle condition.
- The completion of the call when a "waiting" connection is made and the busy line is released, is the same as that hereinbefore described in relation to Figure 1, the engagement with its contact of the middle one of the three top armature switches of trunk ringing relay 273 and the engagement with its contact of the lowermost one of the two bottom armature switches of said relay, allows ringing current from the "A" board to be impressed upon the called for line and as the return path to ground for said current is through the grounded winding of the repeating coil associated with the link connector engaged with trunk jack 267, the calling party receives an audible signal in

the sub-station telephone receiver which assures him that the sub-station call bell of the line he was waiting for has been released from its busy condition and is being rung 5 upon.

For party line ringing the proper key is depressed or manipulated by the operator at the "A" board.

In Figure 17 I have illustrated a more 10 complete embodiment of the adaptation of the system to trunk line work.

As many features shown in Figure 17 have already been amply described, mention will be made only of those features which differ 15 from those illustrated in the preceding figures.

When the "A" operator inserts the calling plug in trunk jack 289 a circuit for the ringing current is closed which may be traced 20 as follows: from the tip spring of trunk jack 289 through the lower winding of trunk relay 290 (which is of low resistance), spring switch 291 and normal contact of trunk calling relay 292 and upper winding of trunk 25 relay 290 (which is of high resistance), completing the circuit to ground and therefore to the grounded terminal of the ringing generator associated with the "A" board. During the intervals between the impression 30 of alternating current on this circuit, the intermittent direct current from the battery interrupter (91 in Figure 1 and 160 in Figure 5) is impressed upon the same circuit and trunk relay 290 is actuated by 35 both of said currents, as are the trunk relays illustrated in the preceding figures. The actuation of trunk relay 290, which is similar to the described trunk relays illustrated in the preceding figures, closes a circuit from grounded battery 293 through trunk ringing supervisory lamp or signal 294. Said lamp or signal is energized by 40 the current flowing through this circuit, its energization always indicating that the called line has not responded.

The busy tests are made in the same way as described in relation to Figure 16.

When trunk plug 295 is inserted in a 50 multiple jack a circuit is closed which may be traced as follows: from ground through the cut-off relay and sleeve contact of trunk plug 295, resistance 296, normal contact and armature switch of trunk controlling relay 297; winding of trunk ringing relay 298, spring switch 299 and normal contact of said 55 relay, waiting interrupter 300 and grounded battery 293, completing the circuit to ground.

If the connection has been made to a busy 60 line, trunk ringing relay 298 is only partially energized, in the manner that has been hereinbefore described, the lowermost one of the two top armature switches engages its two contacts, the engagement with its right hand contact energizing trunk controlling re-

lay 297, which remains energized as long as trunk plug 295 is engaged with a jack, on account of the current flowing in its lower winding.

If the connection has been made to an idle 70 line, trunk ringing relay 298 is fully energized and all its respective armature and spring switches engage or disengage their respective contacts.

Previous to the response of the called sub-station, whether the connection be a "waiting" one or not, if the calling party replaces his receiver upon its switch-hook, trunk relay 290 is de-energized and its armature switch engages its normal contact. As said armature switch is connected to grounded battery 293 and its normal contact connected to the left hand contact of the lowermost one of the two top armature switches of trunk ringing relay 298, which is engaged 80 with its armature switch, the upper winding of trunk controlling relay 297 and the winding of trunk ringing relay 298 are short-circuited and trunk ringing relay 298 is therefore de-energized, the lowermost one of its 85 two top armature switches disengaging its right hand contact first and then its left hand contact, thereby removing the short-circuit made when the armature switch of trunk relay 290 engaged its normal contact. As said disengagement with the right hand contact has already opened the circuit through the winding of said relay and as controlling relay 297 remains energized due to the current flowing in its lower winding, 90 trunk ringing relay 298 cannot again be energized until calling plug 295 is removed from the jack, thereby de-energizing trunk controlling relay 297. The deenergization 95 of the trunk ringing relay restores the called for line to its normal idle condition, allowing the same to test idle at all its associated multiple jacks and restoring the control of the line signal to the sub-station associated with said line.

When trunk ringing relay 298 is fully energized ringing current is impressed upon the line around the winding of trunk supervisory relay 301 from constant ringing interrupter 302 and intermittent battery current is impressed on the line through said winding from battery interrupter 303 in the same way as hereinbefore described in relation to Figures 1 and 5. No interrupter 105 to produce periodic ringing is shown in Figure 17, though one may be used, as may also be used any of the various forms of party line ringing illustrated in the preceding figures.

The return path for the ringing current to the grounded terminal of alternating current ringing generator 304, is through the ring contact of trunk plug 295, uppermost 115 one and engaged contact of the two top armature switches of trunk ringing relay 120 125 130

298, ring spring of trunk jack 289 at the "A" board and thence to ground through the repeating coil associated with the link connector engaged with said trunk jack. As 5 said contact and armature switch of trunk ringing relay 298 are not engaged when a waiting connection is made, the calling party does not receive an audible ringing signal until the called line bell has actually 10 been rung.

When the called party responds, trunk supervisory relay 301 actuates in the same way as described in relation to calling supervisory relay 50 illustrated in Figure 1 and the 15 same relay 157 in Figure 5. The engagement of its armature switch with its alternate contact closes a circuit through trunk calling relay 292 which may be traced as follows: from ground through the cut-off 20 lay and sleeve contact of trunk plug 295, alternate contact and engaged armature switch of trunk supervisory relay 301, winding of trunk calling relay 292 and grounded battery 293, completing the circuit to ground.

25 Trunk calling relay 292 is shown diagrammatically in Figure 17 as performing its functions in a certain sequence; while this illustrated and described sequence of operative functions is not obligatory I prefer its 30 form on account of the absolute assurance it offers that the change from the described ringing connections to the described talking connections will always be carried out in the proper way. As said sequence of operations 35 does not rely on any adjusting means, frequent use of the relay and the consequent wearing away of its contacts and moving members cannot effect said sequence. Also, the described function of battery commutator 40 303 impresses an intermittent direct current on the circuit including the winding of trunk supervisory relay 301; while this relay can readily be made to maintain its armature switch engaged with its alternate contact, 45 without vibrating, when its winding is energized by this intermittent direct current, on account of the great rapidity of the pulsations of said current, to do so entails a comparatively large core for the electro-magnet 50 or a comparatively large armature, or both; as this destroys to a great degree the rapidity of action of said relay, which is most desirable in a supervisory relay, I prefer to use a means similar to the one illustrated in 55 Figure 17, as in that case trunk supervisory relay 301 may be the same class of sensitive relay now used for supervisory purposes and which is well known in the art. It will be readily understood that calling relay 39, 60 illustrated in Figure 1, 118 in Figure 4 and 142 in Figure 5 can be similarly arranged, as their connections are similar in character.

65 When trunk supervisory relay 301 actuates, its armature switch may or may not rapidly engage and disengage its alternate

contact, due to the intermittent current from battery interrupter 303 flowing through its winding, it being immaterial, as far as the actuation of trunk calling relay 292 is concerned, whether such vibration takes place 70 or not. Trunk calling relay 292 is so arranged that its bottom armature switch moves with the greatest freedom, without necessarily incurring any movement of the other armature switch or the various spring 75 switches; therefore if the armature switch of trunk supervisory relay 301 vibrates, momentarily closing and opening the circuit through the winding of trunk calling relay 292, the consequent intermittent energization 80 of the latter is sufficient to start said bottom armature switch vibrating. The great freedom with which said armature switch moves enables it to engage spring switch 305, if not with the first of said vibrations, then, 85 after having vibrated a few times. As said trunk calling relay armature switch is connected to the armature switch of trunk supervisory relay 301 and said spring switch 305 connected to its alternate contact, a 90 bridged circuit is formed around the vibrating armature switch of trunk supervisory relay 301 and therefore the winding of trunk calling relay receives a constant current instead of an intermittent one. This constant 95 current causes its top armature switch to engage spring switch 291 and then to disengage the same from its normal contact, and its bottom armature switch to continue its actuation. The movement of spring switch 100 305 causes the lowermost one of the various spring switches to close a circuit from grounded battery 293, through talking supervisory lamp or signal 306, the energization 105 of the latter always indicating to the operator that the trunk link connector is being used for conversational purposes. The operation of the remaining spring switches takes place in sequence as follows: First, 110 the normal contact of the middle one of the three bottom armature switches of trunk ringing relay 298 is connected to the live pole of grounded battery 293 through winding 307 of the repeating coil; second, the ring contact of trunk plug 295 is connected 115 to ground through winding 308 of the repeating coil; third, and last, spring switch 309 disengages its contact. The first and second described actions may be reversed or 120 so arranged as to be performed simultaneously, the only purpose in the sequence of operations being to insure the making of the connections to windings 307 and 308 of the repeating coil, previous to the disengagement of spring switch 309 from its contact. 125

The described actuation of the top armature switch of trunk calling relay 292 has changed the circuit connections at the "B" board between the tip and ring limbs of the trunk line, said circuit may now be traced as fol- 130

lows: from the tip spring of trunk jack 289, lower winding of trunk relay 290, spring switch 291 of trunk calling relay 292 and engaged armature switch and windings 310 and 311 of the repeating coil, completing the circuit through the ring spring of trunk jack 289 and the link connector apparatus associated therewith.

The upper, high resistance, winding of trunk relay 290 is disconnected from said tip spring when said armature switch disengaged spring switch 291 therefrom and the connection of the series windings 310 and 311 of the repeating coil to said tip and ring springs, furnishes a low resistance path which causes the actuation of the calling supervisory and calling relays associated with the link connector at the "A" board which is connected to said springs.

The disengagement of spring switch 309, of trunk calling relay 292, from its contact opens the circuit through the upper winding of trunk controlling relay 297 and trunk ringing relay 298, the former remaining energized due to the current flowing in its lower winding and the latter being de-energized. The return to normal condition of the two bottom armature switches of the latter relay, disconnects the ringing current from the tip contact of trunk plug 295, and connects said contact to winding 307 of the repeating coil through the spring switch contact already made by the actuation of trunk calling relay 292. The connection from the winding of trunk supervisory relay 301 has been changed in the same manner as hereinbefore amply described in relation to Figure 1. As the lower, low resistance winding of trunk relay 290 is bridged by condenser 312 and as the tip and ring springs of trunk jack 289 are connected through windings 310 and 311 of the repeating coil and the tip and ring contacts of trunk plug 295 are connected to windings 307 and 308 of the same, conversation can take place between the calling and called sub-stations.

When the called sub-station telephone receiver is replaced upon its switch-hook, the winding of trunk calling relay 292 is short-circuited by the engagement of the armature switch of trunk supervisory relay 301 with its normal contact, due to the de-energization of said relay. The consequent de-energization of said trunk calling relay and the disengagement of its top armature switch from spring switch 291 connects the high resistance upper winding of trunk relay 290 to the ring spring of trunk jack 289 and disconnects the low resistance windings 310 and 311 of the repeating coil from the same. Consequently the calling supervisory relay of the link connector engaged with said jack at the "A" board is de-energized and the link connector and trunk line released, in the hereinbefore described manner. The

called line is restored to its normal idle condition in the same manner as has also been hereinbefore described.

As trunk controlling relay 297 remains actuated, the continued disengagement of its lower armature switch from its normal contact prevents the connection of the tip contact of trunk plug 295 to busy test primary 313 of the operator's induction coil, and the same disengagement of its top armature switch prevents trunk ringing relay 298 from again being actuated, as has been hereinbefore described.

In Figure 18 I have illustrated the adaptation of the system to those telephone exchanges where operating conditions make it advisable to trunk all incoming calls, regardless of whether the called for lines are connected to the same exchange or not.

The insertion of answering plug 317 in the answering jack closes a circuit which may be traced as follows: from ground through the cut-off relay and sleeve of the answering jack, sleeve contact of answering plug 317, armature switch and normal contact of answering supervisory relay 318, bottom armature switch and normal contact of controlling relay 319, upper winding of answering supervisory relay 318 and grounded battery 320, completing the circuit to ground. The current flowing through this circuit actuates the cut-off relay and answering supervisory relay 318; the disengagement of the armature switch of the latter from its normal contact opening the circuit as traced therethrough, and allowing the current to flow through the winding of connecting relay 321, which had previously been short-circuited by the engagement of said armature switch of answering relay 318 with its normal contact. Connecting relay 321 is actuated by this current and the engagement of the uppermost one of its two top armature switches with its contacts connects the upper windings of repeating coil 322 to ground, the lower windings of the same being connected to the live pole of grounded battery 320 by the connection of the left hand contact of the bottom armature switch of said relay to the other two contacts thereof when said armature switch engages said contacts. The lowermost one of the two top armature switches of the same relay first engages its right hand contact and then its left hand one, said engagements taking place after the other two armature switches have engaged their contacts. By said engagement a shunt circuit is closed around the lower part of the winding of connecting relay 321 which may be traced from the central terminal of said winding through the connected contacts of the lowermost one of the two top armature switches of said relay and lower part of the winding of controlling relay 319 to the live pole of grounded bat-

tery 320. Controlling relay 319 is actuated by the current so allowed to pass through the lower part of its winding and the disengagement of its bottom armature switch 5 from its normal contact opens the circuit through the upper winding of answering supervisory relay 318 and the lower part of the winding of connecting relay 321. Answering supervisory relay 318 is not de- 10 energized thereby as current is now flowing through its lower winding over a circuit which may be traced as follows: from ground through the uppermost one and engaged right hand contact of the two top armature switches of connecting relay 321, left hand upper winding of repeating coil 322, ring contact of answering plug 317, calling sub-station telephone apparatus, tip contact of said plug, said lower winding of 15 answering supervisory relay 318, left hand lower winding of repeating coil 322, right and left hand contacts of the bottom armature switch of connecting relay 321 (connected together by the engagement therewith 20 of said armature switch) and grounded battery 320, completing the circuit to ground. Connecting relay 321 is not de-energized as current still flows through the upper part of its winding.

20 The operator and the calling party can now converse as the operator's telephone receiver is now connected to the right hand windings of repeating coil 322. The talking circuit for said receiver may be traced 25 as follows: from ground through the uppermost one and engaged left hand contact of the two top armature switches of connecting relay 321, right hand upper winding of repeating coil 322, uppermost one and normal contact of the two top armature 30 switches of operator's relay 323, operator's telephone receiver 324, secondary of operator's induction coil 325, condenser 326, normal contact and bottom armature switch of operator's relay 323, right hand lower winding of repeating coil 322, middle and left hand contacts of the bottom armature switch of connecting relay 321 (connected together by the engagement therewith of said 35 armature switch) and grounded battery 320, completing the circuit to ground. The primary of the operator's induction coil and the operator's transmitter are not shown in Figure 18; their relation to secondary 325 being well known in the art and fully illustrated in Figures 1 and 19.

40 The engagement of the lowermost one of the two top armature switches with its contacts of connecting relay 321 also closed a circuit which may be traced as follows: from ground through supervisory lamp or signal 327, said armature switch and engaged left hand contact, lower part of the winding of controlling relay 319 and grounded battery 320, completing the cir-

cuit to ground. Supervisory lamp or signal 327 is energized by the current flowing in this circuit, said energization always indicating that the calling party has not replaced the sub-station telephone receiver 70 upon its switch-hook.

When the operator inserts calling plug 328 into an idle trunk jack, a circuit is closed which may be traced as follows: from the grounded resistance connected to the thimble contact of said jack, through the sleeve contact of calling plug 328, winding of operator's relay 323, bottom armature switch and engaged left hand contact of connecting relay 321 and grounded battery 320, completing the circuit to ground. Operator's relay 323 is actuated by the current flowing in this circuit and the disengagement from their normal contacts and engagement with their alternate contacts of the uppermost 80 one of the two top and the bottom armature switch of said relay, disconnect the operator's telephone receiver from connection to the right hand windings of repeating coil 322 and connect the latter to the tip and ring contacts of calling plug 328. Therefore, when the proper connection has been completed at the "B" board the calling and called sub-stations are telephonically connected.

95 The engagement with its contact of the lowermost one of the two top armature switches of operator's relay 323, short-circuits the upper portion of the winding of the same, the purpose of which is similar to the one already described, namely, to prevent an accidental or deliberate connection to a busy trunk line, as no connection is made to the tip and ring contacts of calling plug 328 until operator's relay 323 100 has fully actuated. When calling plug 328 was inserted in the trunk jack, if another calling plug 328 was connected to a multiple trunk jack of the same trunk line, and connecting relay 321 associated with said second mentioned calling plug had not been de-energized, then the current from the grounded resistance connected to the sleeve contacts of the multiplied trunk jacks would have two paths offered it, one through operator's relay 323 associated with said second mentioned calling plug, which would have the upper portion of its winding short-circuited as described, and the other through the same relay associated with the first mentioned calling plug. As the latter path would be of a higher resistance than the former it would not receive sufficient current to actuate. As operator's relay 323 115 needs all the current that can flow from the sleeves of the trunk jacks, the same result may be obtained without providing for the short-circuited portion of the winding, but I find in practice that the control of the actuation of the relay is made more reliable 120

by using the same. The same thing applies to the control of all the other relays described in this specification whose windings need all the current that can flow through the sleeves of the respective jacks, in order to accomplish the complete actuation of said relays.

The connection of a busy line to the operator's set or to the left hand windings of repeating coil 322 is prevented by similar means in relation to connecting relay 321. When the answering plug is inserted in a jack, if there is a divided path for the current flowing through the cut-off relay, the complete winding of connecting relay 321 does not receive sufficient current to cause any of its armature switches to engage their contacts, due to the low resistance path offered by the upper part of the winding of said relay which is connected to battery at the link connector already engaged with the busy line.

When the calling party replaces the sub-station telephone receiver upon its switch-hook, the circuit is opened through the lower winding of answering supervisory relay 318 and its armature switch engages its normal contact. The current from the live pole of grounded battery 320, flowing through the lower part of the winding of controlling relay 319 and the two engaged contacts of the lowermost one of the two top armature switches of connecting relay 321 now has two paths offered to it, one through the upper portion of the winding of said relay and one through the lower portion thereof, both paths leading to ground through the sleeve contact of answering plug 317. As these two windings are in opposition to each other connecting relay 321 is de-energized and all the circuits closed by it are opened.

As the engagement with its normal contact of the armature switch of answering supervisory relay 318 is necessary to bring about the de-energization of connecting relay 321, the latter relay is not affected by an accidental or momentary de-energization of said answering supervisory relay.

The de-energization of connecting relay 321 opens all connections to the tip, ring and sleeve contacts of answering plug 317, therefore the calling line is restored to its normal idle condition, as hereinbefore described.

The circuit through operator's relay 323 was opened by the de-energization of connecting relay 321, therefore all connections are opened to the tip, ring and sleeve contacts of calling plug 317 except one which may be traced as follows: from ground through the sleeve contact of said calling plug, upper and lower part of the winding of controlling relay 319 and grounded battery 320, completing the circuit to ground. Said upper part of said winding is of a high resistance so that any further connections

to the trunk line are not impeded, and at the same time controlling relay 319 remains actuated. As the energizing circuit for connecting relay 321 is through the bottom armature switch and normal contact of controlling relay 319 another connection to the trunk line is prevented, should the party at the calling sub-station again remove his receiver before the link connector has been removed from connection with the jack.

Non-inductive resistance 329 is permanently bridged across the lower winding of answering supervisory relay 318, as the latter is initially energized by the current flowing through its upper winding.

The busy test circuit illustrated in Figure 18 is not generally needed as no such tests are usually necessary when connections are made to trunk lines. However, if operating conditions or systems require it, a connection is made from the tip contact of the calling plug to the top armature switch of controlling relay 319, the normal contact thereof being connected either to special primary 330 of the operator's induction coil as shown or to the upper right hand winding of repeating coil 322. In either case the busy signals are produced as hereinbefore described, the continued action of controlling relay 319, after the calling party has replaced the sub-station telephone receiver upon its switch hook, preventing the connection of the tip contact of calling plug 328 to special primary 330, as long as calling plug 328 is inserted in a jack.

It will readily be seen that any of the already described trunk circuits are adaptable for use with the link connector illustrated in Figure 18, the trunk relay illustrated in the various figures being actuated by the direct current from the right hand windings of repeating coil 322, instead of by the ringing current or intermittent direct current of the link connectors described previous to Figure 18. However, as the link connector circuit illustrated in said figure is particularly adapted for use where the "A" operator merely completes a call through to the "B" operator, without communicating with said operator, thereby allowing the calling party to converse with the "B" operator, means whereby the latter can converse with the calling party and signaling means to indicate to said operator which trunk the calling party is connected to, must be provided. Therefore I have adapted the same embodiment of the system illustrated in Figure 17 to meet these requirements and have illustrated the same in Figure 19.

Only the variations from Figure 17 will be described, it being understood that the functions in all other respects are the same as the embodiment illustrated in Figure 17 and described hereinbefore.

In Figure 19 the tip and ring springs of

trunk jack 331 are connected through windings 332 and 333 of the repeating coil with the winding of trunk relay 334. Therefore, when a calling plug is inserted in trunk

5 jack 331 said relay is actuated by the direct current from the repeating coil flowing through said winding, when the link connector illustrated in Figure 18 is used, and if the link connector used at the "A" board 10 is as illustrated in Figures 1, 4 or 5, the winding of trunk relay 334, which is of comparatively low resistance, instantly causes the actuation of the calling supervisory relay, (50 as illustrated in Figure 1, 121 in Figure 13 4 and 157 in Figure 5,) thereby disconnecting 15 the ringing and intermittent direct current and substituting direct current from the respective repeating coils.

The actuation of trunk relay 334 closes a 20 circuit which may be traced as follows: from ground through trunk line lamp or signal 335, normal contact and armature switch of release relay 336, alternate contact and engaged armature switch of trunk relay 334 25 and grounded battery 337, completing the circuit to ground. Trunk line lamp or signal 335 is energized by the current flowing through this circuit, and the "B" operator observing the same depresses connecting key 338, the same being individual to the trunk 30 circuit to which trunk line lamp or signal 335 pertains. Every trunk circuit at "B" operator's position has a connecting key similar to 338; the latter representing the connecting key of the first trunk circuit thereat, connecting key 339 representing that of the middle trunk circuit and connecting key 340 that of the last trunk circuit thereat. The dotted lines between the connecting keys 40 represent the other connecting keys at the "B" operator's position. All the connecting keys at the position are connected as shown, the top spring switch of each key being connected to the normal contact of said spring switch at its immediate right, the spring switch of the last key being connected to ground as shown at connecting key 340, the normal contact of the first key being connected to all the contacts of the uppermost 50 one of the two top armature switches of operator's relays 341 as shown at connecting key 338 and the bottom spring switch of each key being connected to said armature switch of the particular operator's relay which pertains to the same trunk circuit as the key, as is also shown at connecting key 338. The described form of key is preferred, as by its use it is impossible for the operator's telephone set to be telephonically connected with more than one trunk circuit at a time, the connected trunk circuit always being the one represented by the last key depressed or manipulated.

When connecting key 338 is depressed, a circuit is closed which may be traced as

follows: from ground through the top spring switches and normal contacts of all the connecting keys between keys 340 and 338, top spring switch and engaged bottom spring switch of connecting key 338, winding of operator's relay 341, normal contact and armature switch of release relay 336, alternate contact and engaged armature switch of trunk relay 334 and grounded battery 337, completing the circuit to ground. 70 75

Operator's relay 341 is actuated by the current flowing through said circuit and the engagement of the uppermost one of its two top armature switches with its contact makes a connection to the normal contact of the top 80 spring switch of connecting key 338, so that when the operator releases the key, said spring switch, which engages said normal contact before breaking the connection to the bottom spring switch, makes another ground connection to the winding of operator's relay 341 which is therefore not de-energized when the operator releases said connecting key. The engagement with their respective contacts of the lowermost one of the two top and the uppermost one of the two bottom armature switches of operator's relay 341, connects the operator's telephone set 342 to windings 343 and 344 of the repeating coil. Therefore, the operator can 90 95 converse with the calling party who is already telephonically connected to windings 333 and 334 of the repeating coil. The voice currents are allowed to pass trunk relay 334 by means of condenser 345. 100

The engagement with its contact of the lowermost one of the two bottom armature switches of operator's relay 341 connects the tip contact of trunk plug 346 to especial primary 347 of the operator's induction coil, 105 thereby furnishing a means for making the already described busy tests. This connection can be made to winding 343 of the repeating coil instead of primary 347, if desired. 110

When calling plug 346 is inserted in a multiple jack of the called for line a circuit is closed through trunk ringing relay 348 in precisely the same way as already described in relation to trunk ringing relay 298 illustrated in Figure 17, the only difference being that the circuit through the winding of said relay from the right hand contact of the lowermost one of its two top armature switches passes through the upper winding of release relay 336 (Figure 19) as well as through the upper winding of controlling relay 349 (297 in Figure 17). Release relay 336 being energized by the current flowing through said circuit, its armature switch disengages its normal contact and engages its alternate one. The disengagement with its normal contact opens the circuit through operator's relay 341 which thereupon breaks the connection of the operator's telephone 115 120 125 130

set to the repeating coil and that of the tip contact of trunk plug 346 to special primary 347. Trunk line lamp or signal 335 is also de-energized. The engagement of said armature switch with its alternate contact closes a circuit which may be traced as follows: from ground through trunk supervisory lamp or signal 350, lower winding of release relay 336, alternate contact and engaged 5 armature switch of the same, alternate contact and engaged armature switch of trunk relay 334 and grounded battery 337, completing the circuit to ground. Trunk supervisory lamp or signal 350 is energized by 10 the current flowing in this circuit, its energization always indicating that the calling party has not replaced the sub-station telephone receiver upon its switch-hook. Release relay 336 remains energized when the 15 circuit through its upper winding is broken, on account of the current flowing in its lower winding. Therefore the operator's telephone set cannot again be connected to the repeating coil, nor can trunk line lamp or signal 20 335 be energized until trunk relay 334 has been deenergized, which does not take place until the calling party replaces the sub-station telephone receiver upon its switch-hook. 25

In Figure 19 the ring contact of trunk 30 plug 346 is connected to ground, by way of the uppermost one of the two top armature switches of trunk ringing relay 348 and its engaged contact, through winding 343 of the repeating coil, therefore the ringing current returning to ground through said winding produces the described ringing signal in the calling sub-station's telephone receiver. 35

When the called sub-station responds, the 40 actuation of trunk calling relay 351 is the same as trunk calling relay 292 in Figure 17, excepting that relay 351 has no top armature switch, it not being necessary to change in any way the connections of trunk relay 334. 45

If the link connector circuit illustrated in 50 Figure 18 is used at the "A" board then the changes in the ringing circuit indicated by dotted lines 314 and 315, in Figure 17, could not be made either in the embodiment illustrated in Figures 17 or 19, but with the 55 other illustrated forms of link connector circuits said changes could be used in the embodiment illustrated in Figure 19 as well as in that illustrated in Figure 17.

Instead of the lower part of the winding 60 of trunk ringing relay 348 being short-circuited by the complete actuation of said relay, as was trunk ringing relay 298 illustrated in Figure 17, resistance 352 is placed in series with the winding of said relay the 65 same being short-circuited by the complete action of the relay, thereby obtaining the same result as described in relation to the short-circuited part of the winding of said trunk ringing relay 298 illustrated in Figure 17. This resistance may

be used instead of the short-circuited part of the winding of the connecting relay 321 and operator's relay 323 illustrated in Figure 18 as well as for the described short circuited parts of the windings of the relays 70 illustrated in the other figures.

If the "B" operator, after having connected operator's telephone set 342 to a calling line, finds the call cannot be completed through and needs to answer another calling line before inserting trunk plug 346 in a multiple jack, the depression of the connecting key pertaining to the trunk circuit of the second mentioned calling line would break the ground connection from the contact of the uppermost one of the two top armature switches of operator's relay 341 of the trunk circuit associated with the first mentioned calling line, and therefore operator's telephone set 342 would be removed 80 from association therewith. 85

Where more than one connection at a time is not made to any "B" operator, the connecting keys can be eliminated and the upper terminal of the winding of operator's relay 341 connected direct to ground, instead of thereto through said connecting keys. In that event, operator's telephone set 342 would be automatically connected to the calling line whenever a calling plug was inserted in trunk jack 331. In this case if a second call needed to be answered before completing through the first call, trunk plug 346 would be inserted in a device as illustrated in Figure 12 and hereinbefore described. 95

In the preceding description of the various embodiments of my telephone system I have refrained from calling attention to many other combinations of the various disclosed parts, in order not to make this specification interminable, and because said combinations will be self-evident to anyone skilled in the telephone art. Many features may be recombined to form other combinations and in some of the figures I have purposely refrained from illustrating features illustrated in preceding figures, so as to make the understanding of said figures easier and to avoid needless repetition. For example, the combination of colored supervisory signals described in relation to Figure 1 may be used with any of the described cord or trunk circuits, as may be the party line system disclosed therein. Various connections from the supervisory relay armature switches have been shown, which may be recombined. The trunk circuits illustrated in Figure 19 may include the delayed action release of the operator's relay. The sequence of operation of the spring switches of the ringing relay illustrated in Figure 1 and that of the calling relays illustrated in Figures 17 and 19 may be used with any of the described cord or trunk circuits. The special supervisory system illustrated in Figure 7 is 100 105 110 115 120 125 130

adaptable to some of the illustrated trunk circuits, etc., etc.

I have herein shown and particularly described the preferred embodiment of my invention in order that the invention in all of its aspects may be well understood, but it will be seen that the same can be modified and simplified in many respects without departing from the principles involved. For instance, I have shown but one battery, which furnishes current for the signal circuits, as well as the talking circuits. However, if preferred, the signaling circuits could be connected to a separate battery.

15 The actuation of the controlling relay can be made more reliable and economical by connecting the same to a separate battery as it can then be of an increased resistance.

The talking strand circuit of this system 20 is the circuit which includes the tip and ring strands of the link connectors and the circuit connections of these strands to the windings of the repeating coil or to circuits controlled by the relays, individual to each link 25 connector and involved in establishing a connection between sub-stations through said link connector, and the operating strand circuit is the circuit which includes the sleeve strand of the link connectors and the circuit 30 connections of this strand to said relays, excepting the controlling relay, as distinguished from a strand circuit, for example, such as that through the high resistance winding of said controlling relay.

35 Battery commutators or interrupters 91, 160 and 303, can all be connected to a battery of lower voltage than that to which the repeating coils are connected, inasmuch as the supervisory relays are easily energized 40 when not shunted by the non-inductive resistances. In this way, the impressed voltage through the sub-station calling signal apparatus would be less, and consequently the supervisory relays made surer in their 45 operation when the line resistance is changed by the removal of the receiver from its switch-hook.

What I claim is:

1. A telephone exchange system, including 50 telephone lines extending from sub-stations to an exchange having a line relay and a visual line signal at said exchange for each of said lines, a source of variable current, a resistance, an operating circuit for each such 55 line signal including said resistance, said circuit including means controlled by the line relay individual thereto, to impress thereon variable current from said source, and a circuit including said resistance and a 60 winding of the corresponding line relay whereby a variable current due to said resistance will traverse said line relay to actuate the same and at the same time sound an audible signal in the telephone receiver 65 at the calling sub-station provided, however,

that said line signal has first been energized.

2. A telephone exchange system, including telephone lines extending from sub-stations to an exchange having a line relay and a visual line signal individual to each sub-station, an operating circuit for each such signal including a resistance, said circuit including means controlled by the line relay individual thereto, to impress thereon a continuous pulsating current, and a circuit in branch relation to each of said visual line signal circuits and including a winding of its corresponding line relay, said resistance and the primary of an induction coil associated with the sub-station apparatus of a calling line, whereby a current will pass through said resistance and traverse said line relay which will hold its armature contact closed and at the same time sound an audible signal in the telephone receiver at 85 the calling sub-station by means of the connection of said telephone receiver to the secondary of said induction coil, a cut-off relay, and means under the control of an operator and including the cut-off relay associated with the calling line to open said audible signal circuit.

3. A telephone exchange system, including telephone lines extending from sub-stations to an exchange having link connectors 95 for connecting said sub-stations and comprising normally open talking and operating strand circuits individual to the respective link connectors, two relays for each of said link connectors operated respectively when said link connector is connected to a calling and a called line, automatic means comprising said relays to close said strand circuits when establishing a connection between said sub-stations, said strand circuits being 100 opened during an established connection by means comprising said relays and under the control of apparatus at connected sub-stations.

4. A telephone exchange system, including telephone lines extending from sub-stations to an exchange having link connectors for connecting said sub-stations and comprising normally open talking and operating strand circuits individual to the respective link connectors, automatic means comprising a controlling relay to close said strand circuits when establishing a connection between said sub-stations, said strand circuits being opened during an established 115 connection by means under the control of apparatus at connected sub-stations, and automatic means comprising said relay whereby said strand circuits once so opened cannot again be closed until said link connector has 120 been disconnected from the line of the called sub-station.

5. A telephone exchange system, including telephone lines extending from sub-stations to an exchange, link connectors for 130

- connecting said sub-stations and comprising normally open separate talking and operating strand circuits individual to the respective link connectors for calling and called 5 sub-stations, automatic means to close said strand circuits when one of said link connectors is connected to a calling and called line, said strand circuits connected to one sub-station being opened by means under the 10 control of apparatus at said sub-station independent of said strand circuits connected to the other sub-station which are opened by means of apparatus under the control of said other sub-station.
- 15 6. A telephone exchange system, including telephone lines extending from sub-stations to an exchange, link connectors for connecting said sub-stations and comprising normally open separate talking and operating 20 strand circuits individual to the respective link connectors for calling and called sub-stations, automatic means to close said strand circuits when one of said link connectors is connected to a calling and called 25 line, said strand circuits connected to one sub-station being opened by means under the control of apparatus at said sub-station independent of said strand circuits connected to the other sub-station which are 30 opened by means of apparatus under the control of said other sub-station, and automatic means whereby said strand circuits once so opened cannot again be closed until said link connector has been disconnected 35 from the line of the called sub-station.
7. A telephone exchange system, including telephone lines extending from sub-stations to an exchange, a link connector to connect said sub-stations and comprising 40 normally open and separate talking and operating strand circuits individual to the respective link connectors for calling and called lines, automatic means to close said strand circuits when establishing a connection 45 between a calling and called sub-station, a controlling relay, an answering relay, a ringing relay and a calling relay associated with said link connector, means including the de-energization of said three 50 last mentioned relays whereby all the circuits closed by means of the operating strands of said link connector during an established connection therewith are opened excepting the circuit through said controlling relay.
8. A telephone exchange system, including telephone lines extending from sub-stations to an exchange, a link connector to connect said sub-stations and comprising 60 normally open and separate talking and operating strand circuits individual to the respective link connectors for calling and called lines, automatic means to close said strand circuits when establishing a connection 65 between a calling and called sub-sta-

tion, a controlling relay, an answering relay, a ringing relay and a calling relay associated with said link connector, means including the de-energization of said three last mentioned relays whereby all the circuits closed by means of said operating strands during an established connection by way of said link connector are opened excepting the circuit through said controlling relay, and automatic means whereby 70 said circuits once so opened cannot again be closed until said link connector has been disconnected from the line of the called sub-station.

9. A telephone exchange system, including telephone lines extending from sub-stations to a multiple switchboard, link connectors to connect said sub-stations comprising a relay operative when a connection is made to a calling line and a relay operative 80 when a connection is made to a called line and normally open separate talking and operating strand circuits individual to the respective link connectors for calling and called lines, automatic means comprising 85 said relays for closing said strand circuits when establishing a connection between a calling and a called line, a test system, and means comprising said relays under the control of apparatus at one sub-station during 90 an established connection by one of said link connectors to eliminate said test system from the line of said sub-station by opening said talking and operating strand circuits of said link connector connected to the line of 95 said sub-station, and automatic means comprising said second mentioned relay whereby said strand circuits once so opened cannot again be closed until said link connector has been disconnected from the line of the called 100 sub-station.

10. A telephone exchange system, including telephone lines extending from sub-stations to a multiple switchboard, link connectors comprising a relay operative when 105 a connection is made to a calling line and a relay operative when a connection is made to a called line and normally open separate talking and operating strand circuits individual to the respective link connectors for calling and called lines to connect said sub-stations, automatic means comprising 110

said relays for closing said strand circuits when establishing a connection between a calling and a called line, a test system for producing signals distinctive to various conditions of a tested line, and means comprising said relays under the control of apparatus at one sub-station during an established connection by one of said link connectors to eliminate 115 said test system from its line during the time said established connection continues, by opening said talking and operating strand circuits of said link connector connected to the line of said sub-station, inde- 120

pendent of the apparatus at the other sub-station, and automatic means comprising said second mentioned relay whereby said strand circuits once so opened cannot again be closed until said link connector has been disconnected from the line of the called substation.

11. A telephone exchange system, including telephone lines extending from sub-stations to an exchange, line signaling apparatus at the exchange for said telephone lines, link connectors to connect said sub-stations comprising a relay operative when a connection is made to a calling line and a relay operative when a connection is made to a called line and normally open talking and operating strand circuits individual to the respective link connectors for a calling line, automatic means comprising said relays for closing said talking and operating strand circuits when one of said link connectors is connected to a calling line, means governed by the closing of said strand circuits for effacing the line signal of a calling line, and means comprising said second mentioned relay governed by the sub-station apparatus of the calling line independently of the sub-station apparatus of the called line to open said talking and operating strand circuits of said link connector connected to its line thus removing their control over the line signal of the calling line and restoring same to the normal control of said sub-station apparatus of the calling line irrespective of the engagement of the contacts of said link connector with jack contacts of the calling and called lines, and automatic means comprising said second mentioned relay whereby said strand circuits once so opened cannot again be closed until said link connector has been disconnected from the line of the called sub-station.

12. A telephone exchange system, including telephone lines extending from sub-stations to an exchange, link connectors to connect said sub-stations, an operator's telephone set, a special operator's set disconnector, automatic means for connecting said set to the line of a calling sub-station when a connection is made thereto by one of said link connectors, automatic means to disconnect said set from said line when said link connector is connected to the line of a called sub-station, and automatic means to disconnect said set when said link connector is connected to said disconnector.

13. A telephone exchange system, including telephone lines extending from sub-stations to an exchange, link connectors for connecting calling sub-stations to called ones, a double wound supervisory relay for each link connector having one winding connected in circuit with a talking strand thereof, means to initially energize said relay by a current allowed to pass through

the other winding thereof, and automatic means to open the circuit through said second mentioned winding when said link connector previously connected to a calling sub-station, is connected to a called sub-station, 70 said automatic means preventing the closing again of said second mentioned circuit until said link connector has been disconnected from the line of the called sub-station.

14. A telephone switchboard system including a link connector, a supervisory relay related thereto, an answering relay, a circuit closed by the engagement of the armature switch of said supervisory relay with its alternate contact and including the 75 complete winding of said answering relay, the operation of said answering relay maintaining the closure of said circuit through a part only of its winding and short-circuiting the remaining part thereof until the 80 armature switch of said supervisory relay after disengaging said alternate contact engages its normal contact, thereby removing said short-circuit and connecting the previously short-circuited part in opposition to 85 said first mentioned part of said winding of said answering relay and thereby de-energizing the same.

15. A telephone exchange system, including telephone lines extending from sub-stations to an exchange having link connectors to connect said sub-stations, a supervisory signal, an answering relay, a controlling relay and a calling relay, means whereby said signal is only energized when said controlling relay is energized in combination with the energization of one or both of said other relays, the de-energization of said signal indicating the connection established by means of said link connector can be taken down. 95

16. A telephone exchange system, including telephone lines extending from sub-stations to an exchange having link connectors to connect said sub-stations, an answering and a ringing supervisory signal associated 100 with the line of a calling sub-station by means of one of said link connectors, means under the control of apparatus at said calling sub-station to de-energize said supervisory signals associated with its line, independently of the apparatus at the called sub-station, the de-energization of said signals indicating the connection established by said link connector can be taken down. 115

17. A telephone exchange system, including telephone lines extending from sub-stations to a multiple switchboard, a link connector to connect to busy sub-stations, a visual supervisory signal means associated therewith, automatic means whereby when 120 said link connector is connected to a busy line said signal means is not energized until said line becomes idle.

18. A telephone exchange system, including telephone lines extending from sub-sta- 125

tions to a multiple switchboard, a link connector to connect to busy sub-stations, a signal means associated therewith, automatic means whereby when said link connector is connected to a busy line said signal means is not energized until said line becomes idle, and automatic means whereby if the connected sub-station initiates a call said signal means is energized in a different manner.

10 19. A telephone exchange system, including telephone lines extending from sub-stations to an exchange, link connectors to connect said sub-stations, biased calling signal apparatus at said sub-stations, and means to 15 operate the same selectively by an alternating current having succeeding alternations of different strength.

20 20. A telephone exchange system, including telephone lines extending from sub-stations to an exchange, link connectors to connect said sub-stations, biased calling signal apparatus at said sub-stations connected through condensers to the two limbs of said lines, in combination with means for producing an alternating current having succeeding alternations of different strength to operate said apparatus.

25 21. A telephone exchange system, including telephone lines extending from sub-stations to an exchange, calling signal apparatus and other apparatus at said sub-stations, a source of pulsating current, a source of direct current, a relay, a circuit including said calling signal apparatus, said source of pulsating current, one limb of one of said telephone lines and the ground, a separate circuit including said other apparatus, said source of direct current, said relay and both limbs of said telephone line, interrupting 30 means for respectively impressing pulsating current and direct current from said sources upon said circuits, said direct current being impressed upon said second mentioned circuit at intervals between pulsations of said pulsating current which is impressed upon said first mentioned circuit, whereby said calling signal apparatus is actuated by said pulsating current and said relay actuated by said direct current only 35 40 when the two limbs of said telephone line are connected by means of said other apparatus.

45 22. A telephone exchange system, including telephone lines extending from sub-stations to an exchange, link connectors to connect said sub-stations and comprising talking and operating strands, party line ringing keys associated with said link connectors, a key the actuation of which changes 50 the class of current impressed upon one of said telephone lines, and a key the actuation of which actuates said first mentioned key and at the same time reverses the connections to said talking strands.

55 23. A telephone exchange system, includ-

ing telephone lines extending from a plurality of sub-stations having calling signal apparatus to an exchange, link connectors to connect said sub-stations and comprising talking and operating strands, party line ringing keys associated with said link connectors, a plurality of keys for selectively impressing various classes of current upon said talking strands, a plurality of keys for selectively controlling the code ringing of each of said classes of current, and means whereby but one set of code ringing keys is used for the code ringing by means of any of said classes of current.

60 24. A telephone exchange system, including telephone lines extending from sub-stations to a multiple switch board, calling signal apparatus at said sub-stations, link connectors terminating in answering and calling plugs to connect said sub-stations, a local circuit for operating the electro-magnetic mechanism associated with said link connectors, a ringing relay, a source of signaling current, means to automatically prevent the full actuation of said ringing relay when a calling plug associated with one of said link connectors connected to a calling line is plugged into a jack connected to a busy line, said means including a higher resistance in said local circuit including said ringing relay than in said local circuit of the link connector establishing the busy condition of said line, thus preventing the transmission of a calling signal from said source of signaling current to said busy line, and means under the control of apparatus at said busy sub-station to fully actuate said ringing relay, the full actuation of the same reducing the resistance in said local circuit and transmitting said calling signal to said sub-station, said calling sub-station being completely disconnected from said called sub-station until said ringing relay has actuated.

65 25. A telephone exchange system, including telephone lines extending from sub-stations to a multiple switchboard, link connectors terminating in answering and calling plugs to connect said substations, a ringing relay and a calling relay, a source of continuous signaling current, means including the entire winding of said ringing relay to automatically prevent the full actuation of said ringing relay when a calling plug associated with one of said link connectors connected to a calling line is plugged into a jack connected to a busy line, thus preventing the transmission of a calling signal to said busy line, and means under the control of apparatus at said busy sub-station to fully actuate said ringing relay, thereby, short-circuiting a part of its winding and instantaneously transmitting said calling signal to said sub-station, and means also under the control of apparatus at said sub-station, but only after the transmission of said calling signal, to

actuate said calling relay and thereby telephonically connect said sub-station to said calling line, said calling line being completely disconnected from said called sub-
station until said ringing relay has actuated.

26. A telephone exchange system, including telephone lines extending from sub-stations to a multiple switchboard, link connectors to connect said sub-stations and comprising separate talking and operating strands for calling and called lines, a relay in circuit with the calling line operating strand of each of said link connectors, the full actuation of said relay reducing the resistance in said operating strand circuit and said actuation being essential to establish a telephonic connection between two sub-stations, talking and operating contacts associated with each of said telephone lines adapted to be connected respectively to said talking and operating strands, a source of electrical energy, means to close a circuit through said source and a winding of said relay, said circuit including a separate limb for each telephone line from one pole of said source to said contacts and said limb of such resistance as to allow the passage of sufficient current to actuate said relay only when current is not passing from said contacts to instrumentalities of lower resistance used in establishing a telephonic connection pertaining to another link connector, whereby the telephonic connection of a sub-station to a busy sub-station by means of the calling line link connector strands is automatically prevented.

27. A telephone exchange system, including telephone lines extending from sub-stations to an exchange, link connectors to connect said sub-stations comprising a relay operative when a connection is made to a call-

ing line and a relay operative when a connection is made to a called line and normally open talking and operating strand circuits individual to the respective link connectors for calling and called sub-stations, automatic means comprising said relays for closing said strand circuits when establishing a telephonic connection between said sub-stations and means comprising said first mentioned relay and under the control of apparatus at the calling sub-station to open all of said strand circuits after said connection has been established.

28. A telephone exchange system, including telephone lines extending from sub-stations to an exchange, link connectors to connect said sub-stations and comprising normally open talking and operating strand circuits individual to the respective link connectors for calling and called sub-stations, an operator's telephone receiver, automatic means for connecting said receiver to a calling sub-station by way of one of said link connectors when said link connector is connected thereto, automatic means for permanently disconnecting said receiver from said link connector during an established connection of said link connector to a called sub-station line, and automatic means for closing said strand circuits when establishing a telephonic connection between said sub-stations and means under the control of apparatus at the calling sub-station to open all of said strand circuits after said connection has been established.

In testimony whereof I affix my signature in presence of two witnesses.

HUBERT S. TURNER.
